UNITED STATES PATENT OFFICE

JOHN ROYDEN PEIRCE, OF NEW YORK, N. Y., ASSIGNOR, BY MESNE ASSIGNMENTS, TO THE TABULATING MACHINE COMPANY, OF NEW YORK, N. Y., A CORPORATION OF NEW JERSEY

PERFORATED CARD CONTROLLED MACHINE

Application filed September 16, 1930. Serial No. 482,189.

This invention relates to perforated card controlled machines. More specifically, it relates to machines adapted to be controlled by perforated cards to produce other cards similar to the control cards or dissimilar thereto. In my Patent No. 1,506,382, dated August 26, 1924, I disclose a machine adapted to be controlled by a master perforated card for producing notice cards and audit cards.

10 The master card contains numerous fields in which data is printed and perforated. The card is moved step by step to present successive fields to the perforation reading elements to control the printing and perforating of the notice and audit cards. The master card is also divided into several fields adapted to contain records representing an account spreading over a period of several years. Posting and other entries are made 15 in the individual year fields so that in time all of these fields are filled with data and a new record card is necessary to continue the record of an account.

One of the objects of the present invention 20 is to produce a machine that will analyze a control record of the general type shown in said patent and to enter upon a new control record information taken from the old record, thus producing a new record card which 25 may be used in connection with the account in question for the ensuing years or other period.

Another object is to produce a machine of 30 this character which may analyze a record card in several fields successively and reproduce the data taken therefrom upon another card.

Another object is to produce a machine which may analyze a control record card and 35 produce a similar new record or other dissimilar records.

Another object is to devise a machine in which it is possible to cause the machine to analyze a master control record and to 40 produce on a new card certain selected portions of the data contained on the controlling card.

Another object is to devise a machine in 45 which the record taken from a control card may be entered upon the new card in the

form of printing and perforations or in the form of printing only, or perforations only.

Another object is to devise a machine in 55 which the selection of fields of data to be reproduced is controlled by a device which may be set prior to the operation of the machine.

Another object is to devise a machine in 60 which a sub-selecting device may be used to select only certain portions of data in a selected field.

Referring to the drawings wherein I have shown what I now consider to be the preferred form of my invention;

Figure 64 is a detail taken on line 64—64 30 of Fig. 63, and

Figure 65 is a time chart showing the relative times of operation of the various parts of the machine.

The card M of Fig. 2 is similar to the master card used to control operations in the machines disclosed in my copending applications Serial No. 144,661, filed October 28, 1926 and Serial No. 410,057, filed November 27, 1929.

40 The card contains the name and address, the policy or account number and various other data about the account. The card also contains five party fields in which entries are made concerning the account for five consecutive years. Each yearly field is subdivided into four quarterly fields. The first and third quarters of each of the five years are in the upper halves of the yearly fields. The perforated portions of all of these fields 45 are included in the horizontal compound field F extending across the card. The second and fourth quarters are in the lower halves of the yearly fields and the perforated portions thereof are included in the horizontal field 50 G extending across the card.

55 After all of the year fields F and G have been filled with posting and other entries, it is necessary to make up a new master or control card. This is done by putting the old card M through the present machine to control the printing and perforating of the name and other data on a new blank card. Certain data on the old card will be omitted. For instance, the year fields F and G will be 60 left blank for the posting and other entries

to be made during the ensuing years. If the commissions printed on line 8 and perforated in field E are no longer in force they will also be omitted. Or if a new master card is being made up because of a change in the name or address of the person whose account is represented on the card, the name and address will not be copied from the old card but will be filled in by an operator on a printing and perforating machine. In transferring data from an old master card to a new one, a plate of the nature of that shown in Fig. 17 and having the appropriate arrangement of perforations therein is selected by the manual setting of a lever. The perforations control the operation performed by the machine during the successive cycles required to make up the new card, and also determine what data shall be reproduced. To suppress particular additional items for the reasons stated above additional levers may be set manually before the machine is started. The specific control plate 10 shown in Fig. 17 has perforations so arranged as to effect the entries shown on card 11 of Fig. 4 90 when the card of Fig. 2 is controlling. The entries on the new card in this instance are printed without the corresponding perforations. The omission of the perforations is determined by the holes in the control plate 95 of Fig. 17. Having omitted the perforations from the card of Fig. 4, the distances between the printed lines thereon are much less than on the master card of Fig. 2. These distances are also determined by the control plate of Fig. 17.

100 In Fig. 5 I show still another type of card 12 that may be filled out under control of the master card. The card 12 is smaller than either the card M or card 11. The data printed on line 1 of this card is selected from the master card under control of a plate similar to plate 10 of Fig. 17 but with a different arrangement of holes. The data perforated in the field 1a of card 12 corresponds to that printed on line 1. The data perforated in field 2a represents the data printed on line 2. In the card M of Fig. 2 the perforated data corresponding to that printed on line 1 is contained in field A directly below line 1. In making out a new master card the printing and punching will be in the same relative positions as in Fig. 2, as the machine is adapted to normally make the perforated entries directly below the corresponding printed data. On card 12, however, the perforations are a greater distance below the corresponding printed data. Thus, all printed data occupies the upper half of the card and all perforated data, the lower half. The reason for this difference is that the card 12 is for use in tabulating machines similar to that shown in my application Serial No. 682,365 filed December 24, 1923. In making out cards like card 12 then, the control plate 110

besides determining what shall be taken from the master card and whether it shall be entered on the new card in the form of perforations as well as printing, also determines where the perforations shall be made.

5 These are only representative examples of the different sizes of cards and arrangements of data that may be made out on the machine under control of a master card and a plate 10. In Fig. 21 fifteen of the plates 10 are shown. These plates are selected by a manual setting and moved to position for controlling. Fig. 19 shows a chart 13 of ten designations, representing ten of the plates, 15 and an index pointer 14 for aiding in making the selection. The pointer is moved opposite a designation representing the plate being selected. This places the corresponding plate in operative position. Of the ten designations on the chart 13 the first five represent plates for controlling the making out 20 of five different kinds of cards, while the last five represent five plates for controlling the making out of new master cards where 25 any one of five different groups of items may be omitted from the new card. For instance, if the new cards are to contain all of the data that is on the old cards except the data representing age, plan and amount, the pointer 30 will be moved to the designation M. C. AGE, PLAN, AMT. If it is desired to omit these and additional items from the new card this is effected by the setting of one or more of several levers 15 (Fig. 19). A chart 16 35 shows opposite each lever, a designation of the item which that particular lever will cause to be omitted from the new card.

The machine in general

40 Referring generally to the machine, Figs. 6 and 6a taken together represent a plan view with the covering removed. The master or control cards M are placed in a supply hopper or pocket 17 and are adapted to be fed 45 one at a time by the card feeding shuttle 18 into position at M' to be analyzed. From this position the cards are fed by the shuttle into a discharge pocket 19. The new cards N which may be similar to cards 11 or 12 50 or some other kind are placed in a supply pocket 20 and are fed one at a time by the shuttle 21 into position at N' where the entries, printing or printing and perforating, are made. From this position the cards are 55 fed by the shuttle into the discharge pocket 21a. The master cards in the position M' are analyzed by sensing pins 22 which, through intermediate mechanisms, control the setting of punch selector bars 23 and type carrier bars 24 to effect punching and printing 60 of the new card in the position N'. Fig. 11 which is a vertical section through the sensing and printing and punching mechanism shows one vertical row of six sensing pins 65 22. There is one such vertical row of pins

for each column of printed and perforated data on the master card, in the present case thirty two. In Fig. 51 the pins are shown in enlarged detail with the master card in position to be analyzed. The card is fed to 70 position with the perforated field A (see Fig. 2) adjacent to the ends of the sensing pins. As the field A contains only numerals, only 75 the four upper pins of each column will be utilized and the two lower ones will press against the unperforated portion of the card, i. e. the space occupied by the printing of line 2.

Being unable to advance these lower pins will have no effect in controlling printing 80 and punching. The reading of this field and the printing and punching of the new card under control thereof takes place during one cycle of operation of the machine. The master card is then raised to move the 85 perforated field B into position to be sensed by the pins. The sub fields B¹ and B² may be read during the same cycle. The fields C and C¹ cannot be read at the same time by 90 the pins in their present arrangement as the field C¹ reaches above field C. Also field C² reaches up into field C. The card is therefore raised after finishing with fields B, B¹ and B² so that the pins may read the holes in field C¹. These are the pins of the 25th to 95 30th columns inclusive. The pins of all the other columns will have their readings suppressed. Only four pins in each column will read the holes in field C¹, the two lower ones will press against the unperforated portion of the card and have no effect. In the next cycle the card will be raised slightly so that field C will register with the pins. During this cycle the pins of the 25th to 100 30th columns will have their readings suppressed while all the others will be free to control. In the next cycle the card is raised to present field C² to the pins. Columns 25 to 30 will then control and all other columns will be suppressed. Field D will next be 105 read with columns 25 to 30 suppressed. The card is then raised to present the holes in field D¹ to the four upper pins and these columns will control while all others will be suppressed. In reading field E only the four 110 upper pins are utilized; the two lower ones being obstructed by the card. Field F reaches across the card. In reading this field certain of the sensing pins are locked to prevent them from advancing during one cycle and are free to advance during a subsequent cycle while others are locked. The free pins, during their cycles, control the entries on the new card. The operation is the 115 same with respect to field G.

While these successive readings are being taken from the master card, the new card to which the data is being transferred must be moved step by step so that the entries may 120 be made on successive lines. The extent of 125

the movement is variable and is determined by the control plate.

In transferring data from the control card to the new card, the transfer is made straight through the machine so that data taken from a given position on the control card is normally entered in the same or corresponding position on the new card. This order may be changed, however, so that data taken from columns near one side, for instance, of the master card may be entered near the middle or the other side of the new card. Thus, the amount of insurance on the master card which appears in field C² near the right side of the card, is entered on the card 12 of Fig. 5 near the left side of the card. This may be done by shifting either of the cards laterally. In the present case the master card is shifted laterally so as to place the columns to be read in the same vertical planes with the columns on the new card where such data is to be entered. This lateral shifting is also controlled by one of the plates 10.

25 *The control plates in general*

Fig. 16 is a theoretical or diagrammatic view of a control plate containing all of the possible control perforations. The designations near the right edge of the plate indicate successive cycles of operation of the machine. The cycles are numbered from 1 to 17 indicating that the machine may be caused to perform seventeen successive cycles of operations in making out a new card. Identified with each cycle are two horizontal rows of holes. The first thirty two columns of these holes correspond to the thirty two columns of printed and perforated data on the master card.

In Fig. 2 the columns on the card are numbered from left to right. The columns on the plate of Fig. 16 are numbered in the reverse order. The reason for this is that the card faces toward the back of the machine in the sensing position. A hole in the upper row in any column will cause the data in that particular column on the master card to be transferred to the new card. The holes in the lower row under the column headings have nothing to do with the columns of data on the card, but control the extent and direction of movement of the new and old cards, other than the feeding in and out of the cards, during the various cycles. Thus, a hole in any one of the 21st to 32nd columns inclusive in the lower row of the first cycle position will cause the new card to be raised a definite distance during that cycle. Each of these twelve positions represents a movement of a different amount and, of course, the control plate will be perforated in only one of the positions for any given cycle. A hole in any one of the 14th to 18th columns inclusive of the lower row of a given cycle

position will cause the master card to move horizontally a definite distance. And a hole in any one of the 4th to 11th columns inclusive will cause the master card to be moved vertically a given distance. To the right of the numbered columns of perforations or positions are shown twelve additional positions. These positions occur only in the lower row. A perforation in the first of these positions will cause suppression of printing on the new card, of the letter A or any other character shown in the 16th column of the first line on the master card. This may be done where the character has been preprinted on all of the new cards.

This suppression, however, does not affect the punching in that column of the new card. A hole in the second position causes the new card to drop. This is done where the new card is large and the upper printing line is above the line of type. The dropping of the card places the upper line in proper position to be printed on. After that, the stepping up of the card will be controlled by the perforations previously described. A hole in the third position suppresses all punching of the new card. Holes in the next two positions will cause the new card and the master card respectively, to be returned downwardly from a raised position to normal position. A hole in the next position will cause the shuttles to feed cards. That is, the master card will be fed from sensing position and the next one fed in, and the new card will be fed from printing and punching position and the next one fed in. A hole in the next position causes a change in the relative positions of the type and punches so that the punching shall be effected a greater distance below the printing as on card 12 (Fig. 5). A hole in the next position suppresses printing while permitting punching. This is used in making entries in fields F and G. Three cycles are used in making these entries without shifting the new card. In one of these cycles the perforations are made in the small squares 25 within the quarterly fields 26. No printing is done when these perforations are made. In the next cycle the perforations in the quarterly fields 26 are made. At the same time the corresponding printing is effected at 27. In the next cycle the perforation at 28 in the H position or in the O or L position on either side, is made and no printing is effected.

A hole in the next position suppresses the pins which read the month and day perforations in field 26 on the master card. This will suppress the entry, both printing and punching, of this data on the new card. A hole in the next position suppresses the pins that read the open item holes in the squares 25 to suppress the making of this entry on the new card. A hole in the next position

causes the master card carriage, after it has been moved horizontally, to be returned in the opposite direction to normal position. A hole in the last position suppresses the pins 5 that read the OHL positions on the master card, so as not to carry any entries in these positions over to the new card.

The means for selecting one of the plates 10 (Fig. 21) and raising it to position so 10 that the perforations may be sensed to control the machine will be described presently.

Main drive and clutch box

The machine derives its power from an 15 electric motor 30 (Figs. 1 and 9) connected by a belt 31 to a pulley 32 (see also Fig. 14) fixed on a shaft 33. This shaft reaches into the clutch box 34 and has fixed thereon a worm 35 meshing with a worm wheel 36. The 20 worm wheel is fixed on a sleeve 37 (Fig. 45) rotatably mounted on a shaft 38. When the motor is running the worm wheel 36 will be turning. Fixed on either side of the worm wheel are clutch discs 39, 40. Also fixed to 25 the worm wheel between the wheel and clutch disc 39 is a cam 41.

A sleeve 42 loose on shaft 38 carries a spring-pressed clutch dog 43 adapted to engage in a notch 44 in the plate 39 so that the 30 rotation of the worm wheel 36 may cause the sleeve 42 to rotate. Fixed on the sleeve 42 is a bevelled gear 45 meshing with two bevelled gears 46, 47 (see also Fig. 14) mounted on shafts 48, 49.

35 Rotation of these shafts effects operation of the card shuttles and card pickers for feeding cards. Fixed on the shaft 38 is a sleeve 50 having a clutch dog 51 adapted to engage in a notch 52 in the clutch plate 40 to 40 cause rotation of the shaft 38. A stop arm 53 pivoted at 54 is provided to effect de-clutching of the dog 43 from the clutch disk 30. By rocking the stop into the path of the dog 43 the projection 55 is adapted to ride up the incline 56 until it strikes the stop shoulder 57. This will lift the dog out of engagement with the clutch disk and then stop the rotation of the sleeve 42 and shafts 48, 49. To cause these shafts to rotate, the 45 stop 53 may be rocked in the opposite direction to release the clutch dog permitting it to be moved by its spring into cooperation with the rotating clutch disk 39 so that when the notch 44 passes under the dog the latter 50 will drop in and be carried around by the rotating parts thus causing shafts 48, 49 to rotate to effect card feeding. A similar stop 58 pivoted at 59 is provided for effecting de-clutching of dog 51 from clutch disk 40 and operates in the same manner. An additional stop 60 pivoted at 61 is provided for disengaging the dog 51 from its clutch disk. This latter stop is controlled by emergency devices to cause the machine to stop at 65 an intermediate point in the cycle of oper-

ation in order to prevent breaking of parts when something in the machine fails to perform properly. This will be described later. The shaft 38 drives all of the mechanisms for analyzing perforated cards and for transferring the readings to new cards. Fixed on shaft 38 (Fig. 9) is a gear 62 meshing with a gear 63 fixed on a cam shaft 64. The gear 63 also meshes with the gear 65 (Fig. 8) fixed on a second cam shaft 66. Shafts 64 75 and 66 are provided with cams and other operating devices for operating the various parts of the machine.

Start and stop keys

In Fig. 14 the start key is shown at 67 and the stop key at 68. The shank of the start key is provided with a projection 69 reaching over toggle arms or links 70, 71. The toggle arm 71 is pivoted at 72 and is attached at its outer end to the stop key 68. The link 70 is connected to an arm 73 pivoted at 74 and fixed with respect to a slotted arm 75 which is also adapted to rock about the pivot 74. The slot end of arm 75 as shown in Fig. 44 cooperates with a pin 76 on an arm 77 pivoted at 78 and fixed with respect to a finger 79 also adapted to rock about pivot 78. Finger 79 reaches over a pin 80 fixed in a link 81 which is connected at its opposite end to an arm 82 fixed on shaft 54 with the stop 53. A spring 83 connected to an arm 84 also fixed on shaft 54 tends to rock the arm 53 into position to engage the clutch dog. This will in turn move the link 81 toward the right as viewed in Fig. 44. A latch or hook 85 is connected to an arm 86 fixed on shaft 87 on which is also fixed an arm 88 carrying a cam follower roller 89 cooperating with the cam 41. The cam is constantly rotating while the motor is in operation so that the latch 85 is constantly reciprocating to the right and left, a spring 90 acting to cause the cam follower to cooperate with its cam. When the start key is depressed, the finger 79 will be raised permitting the spring 91 to raise the link 81 so that the pin 80 will be engaged by the hook 85 and will be moved by the cam 41 to the left. This will rock the stop 53 out of cooperation with the dog 43, permitting the latter to rock into cooperation with the clutch disk 39. This will cause the sleeve 42, and the shafts 48 and 49 to operate. After the start key has been depressed moving the toggle members 70, 71 below their dead center, the key when released, will be raised to normal position by a spring 92, but the toggle will remain in its depressed position and the stop key will be in upper position.

Depression of the stop key will restore the toggle to its normal position rocking the arms 75, 77, depressing the finger 79 to move the pin 80 out of the path of the latch 85.

When the start key is depressed to throw in the clutch dog 43 it institutes a card feeding cycle, that is, a card is taken from each of the supply pockets and fed into the reading positions of the master and new cards. The clutch is thrown out at the end of this cycle and the machine clutch dog 51 is thrown in to cause the cam shafts to operate to effect reading of the master card and printing and punching of the new card. Several cycles are required for these operations and during this time the card feeding mechanism is idle. The throwing in of the machine clutch member 51 is effected by a link 81a which is similar to link 81 and which is controlled by a hook 85a which is similar to the hook 85. The hook 85a is connected to an arm 86a fixed on the shaft 87 with the arm 86 so that as this shaft rocks it reciprocates the hook 85a as well as the hook 85. If the link 81a is in its upper position as in Fig. 48 the pin 80a will be in the path of the hook 85a so that as the latter moves to the left it will move the link 81a to the left also as viewed in Fig. 46. This will actuate arm 82a to rock the shaft 59 clockwise to remove the stop member 58 from the clutch dog 51. The latter will then cooperate with its clutch disk to cause the cam shafts to operate. After the clutch has been released and the shaft 38 commences to turn a spring 83a connected to arm 84a on shaft 59 will rock the stop 58 back to the position of Fig. 46. As long as the operating shafts are to operate, however, a link 81a will remain in its upper position and will be actuated each cycle to throw the stop 58 out of the path of the clutch dog 51 so that the latter will remain in cooperation with the clutch disk and the shaft 38 as well as the machine cam shafts will continue to turn.

At the end of a series of machine cycles a link 81a will be lowered out of the path of the hook 85a so that the cam shafts will cease to operate and the link 81 will be released so that it may rise into cooperation with the hook 85 to move the stop member 53 thus releasing the clutch dog 43 and instituting a new card feeding cycle. This will feed out the master card and the new card from operative positions and feed new cards into these positions after which a new series of machine cycles commence. Referring to Fig. 14 the shaft 38 is shown as having fixed thereon a collar 38a having a shoulder with which a pawl 38b is adapted to cooperate. This pawl is pivoted at 38c and is held by gravity against the stop collar 38a when the shaft 38 is being stopped by the stop member 53 of Fig. 44 pawl 38b will ride off from the high portion of the collar 38a onto the lower portion just before the clutch dog 43 strikes the shoulder on the stop member 53. The shaft 38 will then be prevented from rebounding or tending to move backward by

the pawl 38b in cooperation with the shoulder on the collar 38a. A similar collar 48a is provided on the shaft 48 and cooperates with a pawl 48b which is similar to the pawl 38b. This will prevent rebound action of the shaft 48 and this control will be transmitted through the bevelled gears 46, 45 and 47 to the shaft 49. This will, therefore, also prevent rebounding of the latter shaft when the card feed clutch is thrown out.

There are conditions under which the pin 80 is held down below the finger 79 as in Fig. 50 so that the raising of the finger by the depression of the start key will not permit the pin to rise into cooperation with the latch 85. In order that the machine may be started under these conditions, the start key shank is connected to a bell crank 93 (Fig. 14) pivoted at 74 and connected to an arm 94. The arm 94 is connected to an arm 95 (see Fig. 44) pivoted at 96 and fixed with respect to a plate 97 to rock the latter about the pivot 96. The plate 97 carries, by pin and slot connection, a finger 98 which is held in its upper position by a spring 99. When the pin 80 is in its lowermost position as in Fig. 50 it will lie adjacent to the side of finger 98. When the start key is depressed to raise the finger 79 link 94 will move to the left as viewed in Figs. 14, 44 and 50 rocking the plate 97 and finger 98 counterclockwise. Thus if the pin 80 is in the lower position it will be engaged by the finger 98 and the link 81 will be moved to the left to disengage the stop 53 from the dog 43.

Control card feeding mechanism

In Fig. 7 the card picker is shown at 100 slidably mounted on guide rods 101. An arm 102 is connected at its upper end by pin and slot to the picker 100 and is pivoted at 103 and connected at its lower end to a link 104 which in turn is connected by a pin and a lost motion slot to an arm 105 fixed on a shaft 106 on which is also fixed an arm 107. The arm 107 is connected by a link 108 to a crank arm 109 fixed on shaft 49 (see also Fig. 14). Thus when the shaft 49 turns a revolution it will cause the card picker 100 to reciprocate, moving a card M forward to the position M2. The card will be carried from this position by card clips 110 and 111 to a sensing position M1. At the same time, if a card is already at the position M1 it will be taken by clips 113, 114 and carried to the discharge hopper 19.

Clips 110 to 114 are all mounted on a card carriage or shuttle 18 slidably mounted on guide rods 116, 117. The upper and lower members of card shuttle 18 are connected together by a yoke 118 which is connected by a link 119 to an arm 120 pivoted at 121 and fixed with respect to an arm 122 connected by a link 123 to the arm 107 so that as the arm 107 is rocked back and forth by the link

- 108 the card shuttle will be moved back and forth on the rods 116 and 117. The parts are timed to move so that the card in the supply hopper 17 is advanced to the position 5 M2 as soon after the commencement of the feeding stroke as the lost motion in the link 104 has been taken up. During this time the shuttle 115 is moved from the left to the right to get the card which is being advanced. 10 During the second half of the cycle the card picker returns to normal position while the card shuttle moves to the left carrying with it the card taken from the M2 position and also a card taken from the M1 position, if it 15 finds one in the latter position.

As shown in Fig. 63 the card clips 110 comprise inner and outer jaws 124, 125 pivoted at 126 on the shuttle 18. The jaw 124 is provided with a rearward projection 124' 20 and jaw 125 is provided with a rearward projection 125' both of which projections are interconnected by a spring 127. The action of the spring tends to close the jaws to grip the card. Also pivoted at 126 and fixed with 25 respect to the jaw 124 is a bell crank arm 128 connected to a link 129 which is connected at its other end to a spring 130 tending to move the link to the left to thus rock the assembly clockwise about its pivot 126 to 30 move the card clip jaws out of the plane of the card M so that after the card carriage is moved to the left and the cards have been released by the clips, the clips may then be rocked to a position to one side of the 35 cards and may be moved to the right through paths which are not obstructed by the cards.

The bell crank 128 is provided with a roller cam follower 131 which, as the card carriage moves to the right and nears the end of its 40 stroke, engages and rides upwardly on the cam arm 132 rocking the clips counterclockwise into position to grip the card which they are approaching. Jaw 125 is also provided with a projecting arm 133 adapted to engage 45 a pin 134 fixed to the carriage or shuttle. When the card clips are rocked outwardly to position to grip a card the projection 133 will engage the pin 134 and stop the jaw 125 when it has been moved to the plane of the card. 50 The jaw 124 will continue to move a little further and thus be separated from the jaw 125 so as to permit the jaws to approach the card in an open condition. After the jaws have straddled the edge of the card the end of 55 the bell crank 128 will strike pin 135 carried on a latching arm 136 which is pivoted at 137 and connected by a spring 138 to the cam arm 132. The arm 136 will then be rocked outwardly to release the arm 132 and the latter 60 will be rocked downwardly by the spring 138. This will release the bell crank 128 and permit the spring 130 to rock the bell crank clockwise thus freeing the jaws of the card clips and 65 permitting the spring 127 to close the jaws over the card to grip the latter. As the card

carriage then moves to the left it will pull the card along with it. The card clips 113 are constructed substantially similar to clips 110 and are controlled by the link 129 which is connected at its left end to the arm 139 pivoted at 126' and which performs the same functions with respect to clips 113 that the bell crank 128 performs with respect to clips 110. The clips 113 will thus grip a card standing in the M1 position at the same time that the clips 110 grip a card standing in the M2 position and both cards will be fed to the left at the same time, the card taken from the M2 position being moved to the M1 position and the card taken from the M1 position being fed to the discharge hopper 19.

When the bell crank 128 rocks to move the card clips to operative positions and also moving the link 129 to the right the latter will be latched in this position by a latching member 140. The spring 130 is also connected to the member 140 to move it to latching position over the rear edge of the link 129. When the card carriage reaches the end of its left hand movement a lower projection 141 of the arm 140 will engage a stop 142 and will be rocked counterclockwise as viewed in Fig. 63 to release the link 129 permitting it to be moved to the left by its spring 130 to permit the card clips to rock out of the plane of the card as previously described. When the link is latched by the latch 140 the card clips will be held in the plane of the card and the spring 130 will not tend to rock the clips and thus press the card out of its plane. The lower clips 111, 114 are connected to the upper clips 110, 113 by shafts or rods 126, 126' to operate at the same time under control of the bell crank arm 128. This mechanism is well known in the art and therefore need not be described in full detail here. After the card shuttle has moved to the left and before it returns to the right, the cam arm 132 will be restored to latched position by a bell crank 132a (Figs. 63, 64) connected by link 132b to an arm 132c (Fig. 7) on shaft 132d. A link 132e running to an arm 132f (Fig. 9) is adapted to rock shaft 132d to pull the link 132b down to restore the cam arm 132. Arm 132f is pivoted at 132g and reaches across the path of the pin 216 in arm 217. When the pin rises it rocks the arm 132f. Link 132b is connected also to the lower card clips as at 132h (Fig. 7). Another link 132i (Fig. 8) performs the same functions for the new card clips as link 132b performs for the old or master card clips. This link is connected to an arm 132j which is also fixed on the shaft 132d.

Shifting of the control card

When the control card is in the M1 position it is adapted to be moved up and down in order that the reading pins may read the different fields of perforated data and it is also

adapted to move laterally so that a particular group of pins may read a particular part of one of the fields of perforated data in order to transmit such data to a different position on the new card. To effect these movements the card is carried in a frame 145 (Figs. 7 and 28). The frame is mounted on a carriage 146 which is in turn supported on frame 147 and is provided with bearings 148 to permit lateral movement of the carriage. The frame 145 is movable up and down in the carriage, 146 being held in position by guides 149. The frame 145 has slots 150 cooperating with pins 150a on a frame 151, the slots permitting frame 145 to move laterally with respect to frame 151. The raising and lowering of the card is effected by raising and lowering the frame 151. For this purpose the latter frame is provided with racks 152, 152' engaging gears 153, 153' mounted on shaft 154. Shaft 154 is provided with a clutch member 155 adapted to cooperate with a clutch member 156 for operation. The clutch member 156 is fixed to gear 157 which meshes with a gear 158 (Fig. 19) on a shaft 159. Shaft 159 has fixed thereon gear 160 meshing with gear 161 which in turn meshes with gear 162 on shaft 64 which as shown in Fig. 9 is driven through gears 63, 62 and shaft 38 which are constantly running when the machine clutch dog 51 is in operative position in the clutch box. Thus the clutch member 156 is constantly running when the shaft 38 is operating. By moving the clutch member 155 into cooperation with member 156 the gears 153, 153' are caused to operate to raise the frames 151 and 145 with the master card.

The clutch is thrown out a definite time after having been thrown in to control the distance that the card is raised. After declutching, a pawl 162a cooperating with ratchet 162b will prevent the parts from returning. The means for controlling the clutch will be described presently in connection with the various controls which operate under control of perforations in the master control card. In order to lower the card from a raised position the pawl 162a is disengaged from the ratchet 162b and the frames are permitted to drop. The speed at which the card and frames drop is controlled by a governor 163 (Fig. 36) connected to shaft 164 having a pinion 165 meshing with a gear 166 fixed on shaft 154. Gear 153' is fixed on shaft 154. A pawl 167 (Fig. 34) carried by gear 153' is actuated by a spring 168 into cooperation with a ratchet 169 fixed through the sleeve 154' to shaft 154. When the gear 153' rotates to raise the card frames, the rotation being counterclockwise as viewed in Fig. 34, the pawl escapes over the ratchet but when the clutch is disengaged and the pawl 162a there- 60 after releases ratchet 162b the frame 151 will turn gear 153' in a clockwise direction. The

pawl 167 then turns the ratchet and with it the gear 166 and pinion 165 and thus operates the governor 163 (Fig. 36) to check the speed of descent. While the weight of frames 145, 151 will cause them to drop when released, a 70 spring drum 169a (Fig. 28) on shaft 154 tends to turn the shaft to lower the frames. A ratchet 169b (see also Fig. 18) on the spring drum is held by pawl 169c to maintain tension. 75

For moving the card laterally the carriage 146 (Figs. 28, 29) has fixed thereto a rack 170 meshing with a gear 171 constrained to turn with clutch member 172 which is adapted to cooperate with clutch member 173 on shaft 80 174. This shaft as shown in Fig. 19 carries a bevel gear 175 meshing with bevel gear 176 on shaft 177 on which the gear 161 is fixed. The shaft 174 is thus rotating when the machine clutch is thrown in. By moving clutch 85 member 172 into cooperation with member 173 the carriage 146 is moved to the right as viewed in Fig. 29. A tape 178 connected to the carriage 146 and to a spring actuated drum 179 is adapted to return the carriage to the left when the parts are released. A ratchet 180 fixed with respect to gear 171 cooperates with a spring actuated pawl 181 which holds the parts in the position to which the clutch moves them so that when the clutch is disengaged the carriage 146 will be held in its moved position against the action of the spring drum 179. By rocking the pawl 181 to release the ratchet the carriage is 90 released to be returned toward the left. The control of the latching will be described presently in connection with the reading of the master card. While not shown the parts may also be provided with a governor similar to 95 governor 163 to control the rate of speed of their return movement. 100

Control card stripper

When the master or control card is fed to the M1 position it is stripped from the feeding clips by a stripping plate 182 mounted by pin and slot 183 on frame member 147' (Figs. 12 and 28). A link 184 (Fig. 52) is connected to the stripping plate 182 and to an arm 185 pivoted at 186 and provided with a cam follower 187 cooperative with a cam 188 fixed on shaft 66. This shaft is constantly rotating when the machine clutch is in. 110

A spring 189 rocks the arm 185 to move the plate 182 across the path of the card so that the card will strike the plate when it reaches proper position in the frame 145. The cam actuates the arm 185 to move plate 182 to the left out of the path of the card. The latch 190 is adapted to cooperate in a notch 192 in the plate 182 to hold it out of the path of the card. The cam 188 is designed to hold the plate in its inoperative position during the greater part of a machine cycle. 120 The plate is adapted to move into card stop- 125

ping position with a sudden motion just before the card reaches this position. The reason for this is that ordinarily a card will be fed from the M1 position during the same stroke that a card is being fed to such position and the plate cannot be moved into stopping position until the rear edge of the last card has passed this position. After the rear edge of the card has passed the position the follower 187 having been released by the cam 188 and the plate 182 being held back by the latch 190, the latch is then lowered and the spring 189 snaps the stop plate 182 into position. As soon as the card strikes the stop and is stripped from the card clips as the card feed shuttle moves on, the cam 188 then engages follower 187 and restores the stop plate 182 to normal position where it is again latched by the latching member 190. The latch member or link 190 as shown in Fig. 7 is connected at its lower end to an arm 192 pivoted at 193 and actuated by spring 194 to latching position. The left end of the arm 192 is adapted to be struck by a pin 195 on arm 196 carried by shaft 49 so that at the proper time in the card feeding cycle the plate 182 will be released. After the card has been stopped and stripped from the clips and the stopping plate has been moved out of position the card must be held in position in its frame as the frame is moved to various positions for reading.

For this purpose stops 197, 198 (Fig. 28) are provided on the card carrying frame 145. In Figs. 30, 31 and 32 the stop 198 is shown as pivoted at 199 on the frame 145 and is provided with an arm 200 actuated by spring 201 to rock the stop into the path of the card. One of these stops engages the upper end of the leading edge of the card and the other the lower end thereof. In Fig. 32 the stop is in its inoperative position; in Fig. 31 it is in its operative position, the card having been stopped by engaging the stop at 202 (Fig. 30). The stops are adapted to be rocked out of position by a cam slide 203 mounted on the frame 145. Hooks 204 carried by the card shuttle (Fig. 63) are adapted to engage the slides 203 on one side to move them to the left as viewed in Fig. 30 out of cooperation with the stops 198 so that the latter may move into operative position. Projections 205 also mounted on the card shuttle are adapted to engage the slides 203 when the carriage moves in the opposite direction to move the slides to the right to rock the stops 198 out of their operative position so that the card may be fed out. As shown in Fig. 63 the latches 204 are fixed on the card clip rod 126 so that when the clips are rocked into position for feeding a card the latches will also rock into position to engage the slides 203. The projections 205 are mounted on rod 126 in position to engage the slides 203 when the carriage moves to the right to get the card.

Latching plate 206 (Figs. 7 and 28) pivoted at 207 on the card carrying frame 145 is actuated by a spring 208 to be rocked into position back of the rear edge of the card after the latter has reached its position M1 to prevent the card from being accidentally moved backward out of position. The card presses the plate 206 out of the way as it is fed in.

New card-feed mechanism

The new cards N are advanced in pocket 20 (Figs. 6 and 8) by a card picker 210 slidably mounted on guide rods 211. A bell crank 212 pivoted at 213 to the frame of the machine is connected by pin and slot at 214 to the card picker and is connected at its other end to a link 215 which as shown in Fig. 9 is connected at its lower end by a lost motion slot and pin 216 to a bell crank 217 pivoted at 218. A spring 219 serves to move the picker to the left as viewed in Fig. 8 to feed the card to the advanced position N2. The bell crank 217 is connected to a link 220 which is connected at its left end to a crank 221 fixed on shaft 48. The card feed shuttle 21 (Fig. 8) is slideable on rods 222, 223. The several portions of the shuttle are connected by a yoke 224 which is connected by a link 225 to an arm 226 pivoted at 227 (see also Fig. 9). An integral depending portion 228 (Figs. 9 and 14) is connected to a link 229 which is connected at its other end to the arm 217 to be actuated from the shaft 48. This moves the shuttle back and forth as viewed in Fig. 8. Card clips 230 on the shuttle are adapted to feed the card from the N2 position to the N1 position and clips 231 are adapted to feed the card from the N1 position to the discharge hopper 21a. It is to be noted that besides the upper and lower clips 230 and upper and lower clips 231 intermediate clips 230 and 231 are provided so that cards of various sizes may be run through this section of the machine to receive data from the master control card. The card clips are similar to those described in connection with the feeding of the master control card and so need not be described in detail. As in the case of the master control card the new card in the N1 position is supported in a frame which is adapted to be moved up and down so that printing and perforating may be effected in various positions on the card.

The card in this instance is not fed laterally as is the control card. In Fig. 8 the broken lines show cards of three different sizes in the N1 position. Only one of these sizes will, of course, be run through the machine at any one time and cards of other sizes than those here disclosed may be used. The frame which supports the card in this position is shown at 232 (Figs. 56 and 61) and is supported by brackets 233 mounted on the frame of the machine. The card being fed from the

N2 position is guided into the N1 position in the frame 232 by guide members 234. Resilient rebound stops 235 are carried by the frame to prevent the card from moving backward after it has once been brought to position in the frame. The card will press the stops out of its plane of movement as it is drawn into the frame and the stops will spring back into position after the rear edge of the card passes. Card stripping stops 236 are provided to be struck by the leading edge of the card when it reaches its position in the frame so that as the card shuttle and clips move on the clips will be drawn off from the card leaving the card in position. These stops are actuated by spring 237 into operative position about their pivots 238. The outer ends of the stops are adapted to be engaged by arms 239 pivoted at 240. Rear extensions 241 of the arms are connected to a link 242 (Figs. 12 and 56) which is connected at its lower end to an arm 243 (Figs. 9 and 14) fixed on a shaft 244 having a follower arm 245 cooperating with a cam 246 mounted on shaft 48. The cam serves to positively pull the link 242 downwardly to rock the arms 239 against the stops 236 to move them out of the path of the card. The spring 247 (Fig. 12) raises the link 242 to move the arms 239 away from the stops 236 to permit the latter to be moved into the path of the card to strip it from the clips.

Fixed to the lower end of the frame 232 are racks 248 (Fig. 61) meshing with gears 249 carried on shaft 250 of a clutch. This clutch is similar to the clutches described in connection with the moving of the card supporting frame for the master control card. The movable clutch member 251 is constrained to turn with shaft 250 while the driving member 252 is fixed on a sleeve 253 loose on the shaft and carrying a bevel gear 254 meshing with bevel gear 254a (see Fig. 15) on shaft 254b. Shaft 254b has a bevel gear 254c (Fig. 19) meshing with bevel gear 254d on shaft 64. The clutch member 252 is constantly rotating while the machine is in operation and the clutch member 251 is momentarily meshed with driving member to raise the card frame and is disengaged therefrom as soon as the card reaches the desired position. The frame is then held in this position by a ratchet 255 on the shaft 250 which is engaged by a pawl 256. The left end of shaft 250 as shown in Fig. 61 carries a spring drum 257 adapted to turn the shaft to lower the card frame. Also fixed on the shaft is a gear 258 meshing with a pinion 259 on the shaft of a governor 260 (see also Fig. 11). The governor serves to control the descent of the frame 232 which takes place when the pawl 256 disengages the ratchet 255.

The card shown in the N1 position (Fig. 61) is a card similar to the master control card of Fig. 2. In this position the field A

of the card is above the punches and the line 1 in which printing is to be effected is above the printing line of the machine. Thus the card must be lowered to bring these parts into proper position to receive data. This is effected by dropping the frame 232 before printing and punching commence.

In Fig. 61 the frame is shown in its dropped position and the upper edge of the card is indicated at N3. The frame is normally held in position to receive a card by latching pawls 261 cooperating with blocks 262 fixed to the frame (see also Fig. 62). The latching pawls 261 are fixed on a shaft 263 on which is also fixed an arm 264 connected to a link 265. The lower end of this link (Figs. 12 and 18) is connected to an arm 266 fixed on a shaft 267 and is adapted to be controlled in a manner to be described later in connection with the reading of the master control card and the controlling of the machine thereby.

Master control card reading pins

The master card in the M1 position (Fig. 11) faces the sensing pins 22. There are in the present instance thirty-two columns of these pins with six pins to each column (see also Fig. 28). The card is first moved to position as we have seen so that the field A on the card may be analyzed by the four upper pins of the entire group. When the field B is analyzed all six of the pins of each column from the first to the twenty-third columns are used. In Fig. 51 the master card is shown between die plates 268, 269. The ends of the pins 22 rest in the perforations in the plate 268 but withdrawn from the plane of the card so that the card may be moved into position. The pins have collars 270 fixed thereon engaged by springs 271 which press against collars 272 loose on the pins. The latter collars engage a slotted comb member 273 fixed in the machine. Springs 271 move the pins toward the right against the card or through perforations therein. A restoring plate 274 engaging all of the collars 270 is adapted to restore the pins to normal position and hold them there.

The two upper pins of each column are connected to a stop bar 275 mounted in a frame 276 and actuated by a spring 277 tending to move the stop toward the left. The pins reach loosely through slots or holes in the flange 278 at the end of the stop. Collars 279 are fixed on the ends of the pins so that the movement of either pin to the right will move the stop 275 with it. The left end of the stop 275 is adapted to cooperate with a stepped projection 280 on a comb 281. The second and third pins from the top are similarly connected to a stop bar 275a and the two lower pins are connected to a stop bar 275b. If the bar 275 remains in the position shown the comb 281 is prevented from de-

scending. If the stop moves to the right one, two or three steps, then the comb is permitted to drop one, two or three steps. If the second pin from the top advances through a perforation in the card, it will move the stop one step to the right being stopped by a stop member 282 striking against the member 273 thus permitting the comb to drop one step. If the upper pin alone moves through a perforation in the card, a stop 283 fixed thereto will engage a projection on stop 282 fixed on the second pin, being thus permitted to advance two steps. It will thus move the stop bar 275 two steps to the right to permit the comb 281 to drop two steps. If both the upper and second pins 22 advance through perforations in the card, the second pin will advance one step until stopped by its stop member 282 and the upper pin will now advance three steps before the stop 283 engages the projection on stop 282. Thus the stop bar 275 will move three steps to the right permitting the comb 281 to drop its full three steps. The third and fourth pins, counting from the top, operate in the same manner to control their stop bar 275a and the fifth and sixth pins also operate in the same manner to control stop bar 275b.

Springs 280a pull the combs 281 down and 30 bail 280b (Fig. 11) restores them and holds them until it is time for them to take a reading. Bail 280b is operated through arm 280c connected by link 280d to follower arm 280e operated by spring 280f and cam 280g. In 35 Fig. 54 the combs 281, 281a, 281b are each shown as having notches 284 along one edge. These notches are of various depths. Associated with each set of combs is a set of stop bars 285 (see Figs. 11 and 54) having lateral 40 projections 286 reaching across the notched edges of the three combs and adapted to move toward the right, in Fig. 54 (or the left in Fig. 11), if all three combs present notches thereto. The distance that the stop bars 285 45 may move to the right depends upon the condition of the notches presented to the particular projection 286. If all three combs present full depth notches to a particular projection 286, that stop will move the full 50 distance or three steps to the right. If any one of the three notches presented is of a lesser depth, the particular stop will move but two steps to the right and if any of the notches is of a still lesser depth, the particular 55 stop will move but one step to the right. The stops are mounted in supporting or guide members 287. Springs 288 connected at one end to the stops 285 and at the other end to restoring bars 289 are adapted when the 60 restoring bars move to the right to tend to pull their stops 285 to the right also. The bars 289 engage shoulders 290 on the stops 285 so that when the restoring bars 289 are moved to the left they will restore the stops 65 to normal position with projections 286 re-

moved from the combs 281. Back of each vertical row of stops 285 is one of the punch selecting bars 23 having fixed thereon a plate 292 having notches and steps reaching out toward the stops 285.

As viewed in Figs. 11 and 60 it will be seen that if any particular stop 285 advances its full distance (to the left) it will be engaged by the upper step on the plate 292 as the particular selecting bar 23 rises. If the stop advances but two steps, it will engage the second step of plate 292 and if it advances but one step it will engage the lower step on the plate 292. The stops that do not advance at all will have no effect upon the positioning of the selecting bar 23. The two lowermost stops 285 are adapted to engage in notches in plate 292 to lock the bar 23 against rising. The restoring plate 274 which permits the pins 22 to take their readings from the card and which thereafter restores them to normal position is connected at its opposite ends to links 293 (Fig. 52) which are in turn connected to arms 294 fixed on the shaft 295. A link 296 connected to an arm 297 pivoted at 304 (Fig. 11) and connected to a cam follower arm 299 works on cam 300 fixed on shaft 66. The rocking of shaft 295 actuates the other end of the restoring plate 274.

The opposite ends of the restoring bars 289 (Figs. 54 and 11) are attached to sliding plates 301 (Figs. 10 and 12). Toggles 302 connected between the plates and the frame of the machine are connected for actuation to arms 303 pivoted at 304. Integral with arms 303 are complementary followers 305, 306 working on cams 307, 308 shaft 66 (see also Fig. 8). The followers and cams are omitted in Fig. 10 in order that other parts may be shown more clearly there but are shown in Fig. 12 and are similar on both sides as indicated in Fig. 8.

The type bar 24 is connected to the punch bar 23 (Figs. 11 and 60) so that both may move up and down together. The connection is such that the relative positions of the type carrier and punch bar may be changed. When reproducing a card such as that shown in Fig. 2 wherein printing is effected on line 1, for instance, and the corresponding perforations are made directly below in the field A, the type bar and punch bar have one relative position, but when producing a card such as shown in Fig. 5 where printing is effected in line 1 and the corresponding perforations are effected in the field 1a the type bar and punch bar have different relative positions. The connection between the type bar and punch bar is effected through an arm 310 fixed to the type bar 24 and provided with a sliding latch 311 adapted to cooperate with a notch 312 in the punch bar 23. The latch 311 is slidably mounted on the arm 310 and may be locked in or out of latching posi-

tion by an impositive latching member 313 actuated by a spring 314. The latch 311 is provided with projections 315 cooperating with a pin 316 on an arm 317 fixed on shaft 318. The rocking of this shaft serves to move the latch into or out of latching position. A spring 319 connected to the arm 310 is adapted to raise the type bar and punch bar. After the punch and type bars have all stopped in positions for punching and printing, individual latching pawls 319a (Fig. 60) are released by a common bail 319b to hold the bars in position against the lifting action of springs 319 after the stop bars 285 have been restored. When the punch bars are restored they will cam the latching pawls out. Before the punch and type bars commence to rise again the bail 319b will be operated to move all of the pawls 319a to the position of Fig. 60. The bail 319b is fixed to shaft 319c on which is also fixed an arm 319d (see also Figs. 10 and 11). This arm is connected by a link 319e to a cam follower arm 319f cooperating with an operating cam 319g on shaft 66.

A restoring bar 320 reaching across the tops of all of the arms 310 is adapted to restore the type bars and punch bars to their lower or normal positions. The restoring bar 320 is connected at its opposite ends to links 321 (Figs. 10 and 12) which in turn are connected to arms 322 loosely mounted on shaft 304 and provided with cam followers 323 as shown in Fig. 12 cooperating with cams 324 on shaft 66. Springs 325 connected to the arms 322 serve to rock the arms to cause their followers to follow the cams. The springs 319 tending to raise the type bars and punch bars will of course also act upon the bar 320 to hold the cam followers against their cams. According to the timing of the machine, after a reading of the card has been taken and the stops 285 have been set, the restoring bar 320 then rises to permit the type bars and punch bars to rise until they are stopped by the stop bars 285. When the type bar is locked to the stop bar in the positions shown in Figs. 11 and 60, punching will be effected directly below the printing as on the card of Fig. 2. When the slide 311 is moved to the left in Fig. 60 the punching will be effected at a greater distance below the printing as in Fig. 5. In this case when the restoring bar 320 rises the type bar 24 will commence to rise while the punch bar remains stationary. A spring 326 connected between the punch bar and the arm 310 holds the punch bar in its normal position against the stop 327 until the arm 310 rises to the dotted line position of Fig. 60 and engages the stop member 292. As the arm 310 continues to rise the stop bar 23 will now also be raised until the stepped stop projection 292 encounters one of the stops 285. The stop bar

23 will then be stopped and this in turn will stop the punch bar 24.

The punches are shown at 328 (Fig. 55) reaching through a die plate 329. There are six of these punches to each vertical row. When moved to the left the punches will be forced through the card M. A die plate 330 is provided back of the card to cooperate with the punches. Back of the punches 328 are interposer plungers 331 having offset projections 332 adapted to cooperate with the punches to force them through the card. These plungers are slidably mounted in the frame 333. The punch bar 23 is provided with a plurality of plungers 334 adapted to cooperate in various combinations with the interposers 331 so as to force the punches in various combinations through the card. Back of the plungers 334 is an operating plate 335 adapted when moved toward the left in Fig. 55 to press the plungers 334 against the ends of the interposers 331 to actuate the punches. In the position of Fig. 55 if the plate 335 were actuated the two upper plungers 334 would be moved to the left but would not actuate any of the interposers 331. Should the type bar 24 and the punch bar 23 be raised one step the type element representing Z will be moved into printing position with respect to the platen 336. The two upper plungers 334 will then be in alignment with the two upper interposers 331 and the third plunger 334 counting from the top will be in alignment with the lowermost interposer 331.

Referring to the diagram of Fig. 3 it will be seen that the two upper punches and the lowermost punch will effect perforations representing the letter Z. Should the type bar and punch bar both be raised two spaces the letter Q will be in position for printing with respect to platen 336 and the second plunger 334 counting from the top will be in alignment with the uppermost one in the interposer 331 while the third plunger 334 will be in alignment with the second interposer from the bottom. These two punches will perforate holes representing the letter Q as shown in Fig. 3. The arrangement of the type elements and of the plungers 334 is such that whenever a particular character is in position for printing, the plungers will be in alignment with the interposers 331 in such combination as to effect perforations representing the character being printed in accordance with the chart of Fig. 3.

To operate the punch actuating plate 335 the sides 337 are connected at 338 (Figs. 10 and 12) to toggles 339, connected at 340 to the frame plates 341 of the machine. Links 342 connected to arms 343 are actuated by springs 344 to break the toggle and restore the actuating plate 335 to inoperative position. The arms 343 are fixed on shaft 345 on which is also fixed an arm 346 having

pin 347 adapted to cooperate with a notch in the lower edge of a link 348. This link is held by spring 349 in position cooperating with the pin 347. Link 348 is connected to 5 an arm 350 loose on shaft 304 and provided with complementary cam followers 351, 352 cooperating with cams 353, 354. The sides 337 of the punch actuating plate 335, as shown in Fig. 55, reach forward and are connected to a perforated plate 355 cooperating 10 with the punches 338 and engaging collars 356 on the punches so that when the plate 335 is moved to the left to actuate the punches the perforated plate 355 will move to the left to 15 permit the punches to be operated.

When the plate 335 is restored to the right in Fig. 55 the perforated plate 355 will restore the punches to their normal positions. It is to be understood that the plungers 334 20 are actuated by springs within the carrying bar 23 to restore them to normal position when the operating plate 335 is restored. This construction is common in this art and need not be shown in detail here.

25 When printing alone is being effected to produce a card such as shown in Fig. 4 the operation of the punches will be suppressed. This may be effected by raising the link 348 (Fig. 10). For this purpose an arm 357 is provided. This arm has a pin 358 reaching under the arm 348 to raise the latter out of cooperation with the pin 347. The arm 357 is pivoted at 359 and is actuated by arm 360 (Fig. 12) connected to a link 361 reaching downwardly and connected at its lower end to an arm 362 on shaft 362a. The manner in which the control is effected will be described later.

40 *Operation of the type*

To operate the type elements 363 (Fig. 55) to effect printing, plungers 364 are provided. There is one of these plungers for each column of type. The plunger as shown in Fig. 45 55 is in horizontal alignment with the platen 336. After the type carriers have all been set the plunger 364 is struck and this in turn strikes the type elements 363 forcing them against the inking ribbon 365 to print upon 50 the card M. Back of each of the plungers 364 is a printing hammer 366 loosely pivoted on a rod 367. A spring 368 is provided to actuate the hammer. A latch 369 normally latches the hammer against operation, a 55 spring 370 serving to hold the latch in latching position. Associated with each latch 369 is a hook member 371 carried by a bail 372 pivoted at 373.

The hooks 371 are held in their upper 60 positions by springs 374 so that normally they may be moved to the left without actuating the latches 369. A link 375 is associated with each of the hooks and when lowered lowers the hooks 371 to position to 65 cooperate with a projection 376 on the cor-

responding latch 369 so that when the hook 371 is moved to the left it will move the latch out of cooperation with the hammer, thus permitting the latter to operate to striking the plunger 364 to effect printing. The link 375 is connected to a lever 377 (Fig. 60) pivoted at 378. The opposite end of the lever is adapted to cooperate with a pin 379 fixed in the punch bar 23. When the punch bar is in its normal position it holds the lever 377 in position to hold the link 375 in its upper position as in Fig. 55. In this position if the hook 371 is moved it cannot release the hammers for printing. When a punch bar 230 rises, however, the lever 377 is permitted to rock under the influence of spring 380. This pulls the hook 371 down so that when the hook is moved to the left it will move the latch 369, thus releasing the hammer for operation. After the hammers have operated to 80 effect printing, they will all be restored by a restoring bail 381. This bail is fixed on the shaft 367 which has fixed thereto an arm 382 (Fig. 10) connected by a link 383 to an arm 384 pivoted at 385 and fixed with respect to an arm 386 which in turn is connected to a link 387. This link is connected at its opposite end to an arm 388 loose on the shaft 304 and provided with complementary cam followers 389, 390 cooperating with cams 391, 392 on the cam shaft 366. Also fixed on the shaft 367 is an arm 393 adapted to cooperate with a shoulder on a link 394 which is connected to an arm 395 fixed on the shaft 373 (Figs. 10, 11 and 55) on which the arms 372 are also fixed.

In its normal position the arm 393 may be a short distance to the right of the shoulder of the link 394 in Fig. 10. Thus when the shaft 367 is rocked counterclockwise in Fig. 10 a sufficient distance to remove the bail 381 far enough from the hammers so that the latter will not strike the bail when released, the arm 393 will then reach the shoulder on the link 394. Further rocking of the shaft 367 will then cause the link 394 to move, rocking the shaft 373. This, in turn will move all the hooks 371 to the left in Fig. 55. All of the hooks that have been lowered by reason of the rising of their corresponding punch and type bars will then operate the latches 369 to release the corresponding hammers 366 to effect printing in those respective columns. After printing has been effected, the type bars as well as the punch bars will be restored. Also the restoring bail 381 will restore all the hammers 366 and all of the hooks 371 will be restored to normal position so that the latches 369 may latch the hammers in their rear positions. When the punch bars have descended to their normal positions they will cause the links 375 to rise, releasing the hooks 371 so that they may move to their upper or normal position as in Fig. 55.

The type plungers 364 are all mounted in 130

a frame 396. A bar 397 attached at its opposite ends to arms 398 is also mounted in this frame. The arms 398 reach into slots 399 in slides 400. These slides have pin and slot connections at 400a with arms 401 fixed on shaft 402. An arm 403 (Fig. 10) is fixed on the shaft 402 and is connected by a link 404 to an arm 405 fixed on shaft 367. Thus when the shaft 367 rocks counterclockwise in Fig. 10 to move the hammer restoring bail away from the hammers it also causes the shaft 402 to rock counterclockwise in Fig. 10 or clockwise as viewed in Fig. 55. This moves the slides 400 to the right in Fig. 55 to move the bar 397 to the right. This, in turn frees all of the type plungers 364 before they are struck by the hammers.

After printing, when the hammers are restored, the slides 400 will be returned to the left thus restoring the bar 397 to the left. This moves all of the plungers 364 back to their normal positions. When the relative positions of the type bars and punch bars are changed in order to print a greater distance above the corresponding perforations, the printing will be effected in connection with the upper platen 336a (Fig. 55). It will be seen in connection with Fig. 60, that when the latching slide 311 is moved to the left so that the type bar 24 will rise with the cross arm 310 to the dotted line positions before the punch bar 23 commences to rise, the type bar will be in advance of the punch bar a distance equal to the distance between the two platens 336 and 336a. Thus when the punch bar 23 is stopped by one of the stops 285 the type element 363 representing the data which will now be punched by the punches 328 will be in alignment with the upper platen 336a. When printing in connection with platen 336a, it becomes necessary to raise all of the type plungers 364 to actuate the type in this upper plane. For this purpose frame 396 is slidably mounted in grooves 406 and is connected to links 407 (Figs. 55, 57 and 11). As shown in Fig. 57 links 407 are provided with pins 408 resting between arms 409 pivoted at 410 and interconnected by a spring 411. An arm 412 is fixed on shaft 410 on which are also fixed two arms having pins 413 resting between the arms 409. The arm 412 is connected by a link 414 (Figs. 57, 60) to the arm 317. Thus when the shaft 318 is rocked counterclockwise to disconnect the type bar and punch bar the link 414 will be pulled downwardly. This will rock the arms 409 upwardly in Fig. 57, raising the links 407 to raise the frame 396 from the position of Fig. 55 to that of Fig. 57.

Plungers 364 will now be in position to effect printing in connection with the platen 336a. The restoring bar 397 has also been raised. By reason of the slots 399 in the plates 400 the restoring bar arms 398 continue to cooperate with the slides 400. To effect

rocking of the shaft 318 (Fig. 60) to change the relative positions of the type bar and punch bar this shaft has fixed thereon an arm 415 (Fig. 59) provided with upper and lower pins 416, 417. A T-shaped link 418 is adapted to cooperate with one or the other of pins 416, 417 to rock the shaft 318. The link 418 as shown in Fig. 12 is connected to a cam follower arm 419 loose on shaft 304 and provided with a roller 420 cooperating with a cam 421 on the cam shaft 66. A spring 422 holds the cam follower against its cam. A spring 423 normally holds the link 418 in its upper position so that when it is moved to the right by the cam it will cooperate with the upper pin 416 to rock the shaft 318 clockwise to move the latching slide 311 into the position of Fig. 60 to lock the type bar and punch bar in normal relative positions. To move the slide 311 to the left to unlatch the type bar and punch bar from each other the link 418 will be lowered against action of its spring 423 so as to cooperate with the lower pin 417 to rock the shaft 318 counterclockwise. Lowering of the link 418 is effected by an arm 424 pivoted at 425 and actuated by a link 426 which as shown in Fig. 12 is connected to an arm 427 on a shaft 428. The rocking of this shaft will be described later in connection with the operation of the various controls.

Means are provided to prevent the accidental rocking of shaft 318. Fixed on the shaft is an arm 318a (Fig. 59) having two notches 318b. A pin or roller 318c is fixed to an arm 318d pivoted at 318e and is pulled by a spring 318f into cooperation with one or the other of notches 318b. A latch 318g cooperates with a pin 318h fixed in the arm 318d to hold the roller 318c positively in engagement with the notches 318b. A link 318i attached to the link 418 is connected at its opposite end to the cam member 318j. When the link 418 is moved to the right the cam 318j cooperating with a pin 318k fixed to the latch 318g raises the latch to free the arm 318d. As the link 418 continues to move, it then engages one or the other of pins 416, 417 to rock the shaft 318. The arm 318a then cams the rollers 318c out of whichever notch it is lodged in and permits it to settle in the other notch as the shaft is rocked to its new position. As the link 418 then returns to its normal or left hand position the cam 318j will release the latch 318g to again lock the roller 318c in cooperation with the arm 318a to positively latch the shaft 318 in the position to which it has been rocked.

125
Machine stops when type fail to restore

Referring to Fig. 57, the type elements 363 are mounted in the type carrier bar 24 with springs, not shown here, for restoring the 130

type element to their normal positions after they have been moved to the right to print in connection with the platen 336. This spring construction is common in this art and therefore need not be shown in detail.

It will be seen that if after printing, any of the type elements 363 fail to return to normal position, they might strike the upper edge of the guide plate 330 when the type bar is lowered and thus be damaged. Means are therefore provided to cause the machine to stop when any of the type elements fail to restore to normal position. This means comprises a feeler plate 429 (Figs. 55, 57 and 11). This plate is mounted on arms 430 by pin and slot connection 431. The arms 430 are attached to frame 396 to be raised and lowered with the type plungers 364. A bell crank 432 pivotally mounted on arm 430 is connected to the plate 429 at one end and to a link 433 at its other end. This link is connected to an arm 434 fixed on the shaft 435. Also fixed on this shaft is an arm 436 connected by pin and slot to slide 400. Thus when the slide 400 is moved to the right shaft 435 will be rocked counterclockwise. This will move link 433 to the right moving the plate 429 to its upper position. A spring pressed latch 437 will cooperate with a lateral projection 438 on the arm 434 to hold the link 433 to the right, thus holding the plate 429 in its upper position after the slide 400 has returned to the left. A spring 439 connected between the arms 434 and 436 will tend to return the link 433 and plate 429 to normal position. As the slide 400 approaches its position to the left, the pin 440 will then engage the lower projection of latching arm 437 and rock it against the action of its spring 439 out of cooperation with the arm 434. This will permit the spring 439 to tend to restore the plate 429 to its normal or lower position. In Fig. 55 this plate is shown in its normal position. It is raised before the type elements 363 are actuated to print. After the printing the plate is permitted to be restored to its normal position as in Fig. 55.

It will be seen that if a type element 363 is not restored to the left the plate 429 will be prevented by this type element from being lowered to its normal position as in Fig. 55. This will prevent the spring 439 from pulling the link 433 to the left and rocking the shaft 435 clockwise in Figs. 55 and 57. 55. Fixed on shaft 435 is a latching member 441 (Fig. 58). A link 442 provided with a lateral projection 443 is connected at its lower end to an arm 444 (Fig. 46) pivoted at 445 and connected to an arm 446. This arm is in turn connected by a link 447 to an arm 448 pivoted at 61 and fixed with respect to the stop member 60 heretofore described. Fixed with respect to the clutch sleeve 50 is a cam member 450 carrying a roller 451 adapted to cooperate with the inner edge of arm

448a. As the clutch dog rotates clockwise in Fig. 46 the roller 451 will rock the arm counterclockwise holding it in this position during a considerable portion of the cycle of the machine. After the roller 451 passes out of cooperation with the left end of the arm 448a the lateral projection 451a continues to hold the arm 448a and the stop member 60 rocked in the counterclockwise direction. When the arm 448 is rocked the link 447 is moved to the left raising the link 442. In Fig. 58 the raising of this link lifts the projection 443 out of cooperation with the latch member 441. The position of the latch 441 in Fig. 58 is that which it assumes when the feeler plate 429 of Fig. 55 is raised a distance permitted by the pin and slot connection 431. After the latch 437 has released the arm 434 the spring 439 rocks the shaft 435 lowering the plate 429 back to its normal position. The rocking of the shaft 435 will then rock the latch 441 out from under the projection 443 while the latter is in its raised position.

If the feeler plate 429 is prevented from being restored to its lowered position by one of the type elements 363 which was not restored, the shaft 435 will be prevented from rocking in a clockwise direction and the latch 441 will remain under the projection 443.

Referring to Fig. 46, after the member 451a passes out of cooperation with the left end of the arm 448a and stop 60 rocks to its outer position and the link 447 moves to the right while the link 442 moves downwardly. If the plate 429 has been restored to its normal position moving the latch 441 out from under the projection 443 the link 442 will be permitted to descend to its lowermost position thus permitting the stop 60 of Fig. 46 to move to its inoperative position. But if the plate 429 is stopped by one of the type elements 363 the latch 441 will remain under the projection 443 preventing the link 442 from moving downwardly and this in turn will prevent the stop 60 from moving to its inoperative position. In other words, the stop 60 remains in position to be engaged by the dog 51 as the latter approaches and the machine will be stopped.

Selection and adjustment of the operation control plate

The control plates 10 shown in Figs. 17 and 21 are all mounted in a frame 452. This frame is provided with threaded sections 453 mounted on threaded rods 454. Bevelled gears 455 fixed on rods 454 (Figs. 18 and 22) mesh with bevelled gears 456 fixed on a rod 457 which in turn is provided with a bevelled gear 458 meshing with a similar gear 459 on a rod 460. Rod 460 has mounted thereon an operating crank 461 (Figs. 18, 19 and 22). Turning of the crank 461 will thus rotate the rods 454, causing the frame 452

to move to the right or left as viewed in Figs. 11 and 21.

By this means any of the plates 10 may be moved into position directly below slot 462 (Figs. 11 and 21). An index 14 carried by the frame 452 cooperates with the scale 463 (Figs. 6a and 19) to indicate which of the several plates is in position ready for operation. In Fig. 19 a scale 463 is marked to indicate the various kinds of control plates that is, control plates for controlling the making of several kinds of duplicate cards. Each of these control plates has a different combination of perforations as in Fig. 17. The particular control plate shown in Fig. 17 is marked data card. According to the scale in Fig. 19 this is the first of the several control plates. If it is desired to duplicate or make out cards under control of this particular plate, the crank 461 will be turned until the index 14 registers with the line marked data in Fig. 19. This particular plate will then be in position to be used. When the frame 452 has been adjusted to locate one of the plates below the slot 462 that particular plate will cooperate with projections 464 (Figs. 17 and 22) carried by a frame 465; the projections 464 reaching into the notches 466 in the plate 10. By raising the frame 465 the perforations in the plate 10 may be brought into alignment with perforations 467 in the plates 468 forming the slot 462. There are two horizontal rows of perforations in the plate 10 for each of 17 cycles of the machine as shown in Fig. 16. One of these rows is designated as the upper row and the other the lower row. The frame 465 is first raised to control the operations of the machine during the first cycle. For this cycle the upper and lower rows of perforations for the first cycle will be in alignment with the perforations 467 in the plates 468.

When the plate 10 is in position below the slot 462 it will be raised part way into the slot by the operation of the crank 469. This crank arm is fixed on a shaft 470 (Figs. 21, 22) on which is also fixed a cam 471 cooperating with a pin 472 fixed in the frame 465. By turning the crank 469 counterclockwise to the position of Fig. 22 the cam 471 will be rocked from the position of Fig. 17 to that of Fig. 22. This will raise the frame 465, moving the perforated plate 10 up into the slot 462 as in Fig. 21.

The parts are so designed that one revolution of the crank 461 as viewed in Fig. 19 will move the frame 452 a distance equal to the distance between the several plates 10. Thus unless the crank 461 is in the position of Fig. 19 the projections 464 of Fig. 17 may be between two of the plates 10 or actually in cooperation with two of these plates. In order that the frame 465 may not be raised unless the frame 452 is in po-

sition properly placing the plate 10 with respect to the projections 464 a disk 473 fixed on the shaft 457 has been provided with a notch 474 (Fig. 21) adapted to cooperate with a sector 475 fixed on the shaft 470 with the crank 469. When the frame 452 is in proper position the slot in the disk 473 will be in position to permit the turning of the shaft 470 as in Fig. 22 and unless the frame 452 is in proper position the shaft 470 and crank 469 cannot be turned to raise the plate 10. After the plate 10 has been raised to the position of Fig. 22 it will thereafter be adjusted by gears 476 shown in Fig. 26.

These gears cooperate with racks 477 fixed on the opposite sides of the frame 465. The gears are fixed on a shaft 478 on which is also fixed a ratchet wheel 479. Actuating pawl 480 carried by an arm 481 loosely mounted on the shaft 478 is pressed by a spring into cooperation with the ratchet wheel 479. A holding pawl 482 is provided to hold the parts in position to which they have been turned by the pawl 480. An arm 483 (Figs. 18, 19 and 26) is loosely pivoted at 484. An arm 485 fixed on the stud 481 is connected by a spring 486 to the arm 483 so that a clockwise turning of the arm 485 will cause the arm 483 to turn in the same direction. An arm 487 provided with a cam follower roller is adapted to cooperate with a cam 488 fixed on the shaft 489. The arm 487 is also fixed on the stud shaft 484 with the arm 485. A spring 490 connected from the frame of the machine to the arm 485 is adapted to cause the cam follower to follow the cam. The shaft 489 (Figs. 18 and 19) is provided with a gear 491 meshing with the gear 157 for operation. Once each cycle of the shaft 489 the arms 487, 485 will be rocked causing the arm 483 to rock first to the left and then back to the right as viewed in Figs. 18 and 36. This will turn the ratchet wheel 479 one notch counterclockwise for each cycle of operation, thus raising the frame 465. The parts will then be held in this position as explained, by the pawl 482.

Fixed on the gear 476 (Fig. 26) is a pawl 492 cooperating with a ratchet 493 loose on the shaft 478 but fixed with respect to a gear 494. The gear 494 meshes with a pinion 495 (Figs. 18 and 22) connected to a governor 496. When the frame 465 is being raised and the gear 476 is turning counterclockwise (Fig. 26) the pawl 492 moves idly over the ratchet 493. When the frame 465 is released and permitted to drop it will turn the gear 476 clockwise and the pawl 492 will then cooperate with the ratchet 493, turning the ratchet and gear 494 and also governor 496. The governor will thus regulate the speed at which the frame is permitted to descend. A spring drum 497 (Figs. 19, 20 and 22) is connected to the shaft 478 and is adapted to

exert a downward pressure on the frame 465. A spring-pressed pawl 498 cooperating with a ratchet 499 is adapted to hold the spring under tension to which it is adjusted by turning of the drum 497. Loose on the shaft 478 is a cam 500 (Fig. 26) integral with an arm 501 and provided with projections which, when the arm 501 is rocked counterclockwise, will cooperate with pins 502, 503 in the pawls 480, 482 to raise the pawls out of cooperation with the ratchet 479. This will free the gear 476 to permit the frame 465 to drop. The arm 501 is connected to a link 504 which is connected at its upper end as shown in Fig. 22 by pin and slot connection to arm 505 pivoted at 506 and provided with a pin 507 cooperating with a slot 508 in the sector 475. When the sector 475 is rocked to the position of Fig. 22 to raise the frame 465 the link 504 is permitted to descend under the action of spring 504a to rock the cam 500 clockwise, thus releasing the pawls 480, 482 for operation.

If it is desired to lower the frame 465 so as to select another plate 10 to control the operation of the machine the crank 469 is rocked clockwise as viewed in Fig. 22. This rocks the arm 505 to raise the link 504 thus rocking the arm 501 and cam 500 counterclockwise as viewed in Fig. 26 to lift the pawls 480, 482 out of the ratchet 479. In order to prevent the turning of the crank 461 to select a new plate 10 before the frame 465 has descended all the way to lower the previously used control plate 10 out of the slot 462, additional locking means is provided to prevent the turning of the shaft 457. This locking means comprises a disk 509 (Fig. 20) fixed on the shaft 457 and provided with a notch 510 adapted to cooperate with a spring pressed latching arm 511. The latching arm 511 is provided with a bent over or flanged end so that when rocked counterclockwise about its pivot 512 it will lock with respect to the slot 510. A rearward portion 511a of the latch 511 (Figs. 17 and 20) reaches under one of the brackets 464 carried by the frame 465. When the frame is in its lowest position it will cooperate with the arm 511a rocking the latch 511 out of the slot in disk 509. If the frame is slightly above its lowest position the latch 511 remains in cooperation with the disk 509. Thus, after the crank 469 has been turned to permit the frame to descend its full distance, the crank 461 cannot be operated until the frame reaches its lowest position to remove the latch 511 from the disk 509.

60 Controlling printing and punching

As we have seen in connection with the master card in Fig. 2 the printed and punched information is contained in 32 vertical columns. To read this information there are 32 columns of sensing pins 22 shown in Figs. 28

and 29. These pins, through intermediate controlling mechanisms, control the setting of 32 type carrier bars 24 and 32 punch controlling bars 23 as in Figs. 11, 55 and 56. The setting of the type bars and punch bars to control printing and punching is controlled by the stops 285 shown in Figs. 11, 54 and 60. The lowest one of these stop bars has no lateral projection 286 provided on the rest of the stops to be controlled by the combs 281. This lowest stop 285 then is normally free to advance when the restoring bars 289 operate. The bar will then normally move into a notch 292a in the projection 292 to prevent the punch bar 23 and type bar 24 from rising. In printing a new card under control of the master card of Fig. 2 one of the plates 10 (Figs. 17 and 21) is used to control the selection of data from the master card to be reproduced on the new card.

Referring to Fig. 16 the perforations as we have seen are divided into 17 cycles and there are two horizontal rows of perforations to each cycle. In other words, there is an upper and a lower row of perforations to each cycle. In the upper row there may be 32 perforations representing the 32 columns of data on the master card. Wherever it is desired to reproduce information from a particular column on the master card a perforation in the upper row on the control plate will cause the machine to read the data on the master card and will reproduce it on the new card.

In reading the perforations contained in the field A on the master card which is done in the first cycle, the machine will be controlled by the perforations of the first cycle of one of the control plates 10. If it is desired to reproduce all of the data contained in the field A and printed on line 1 of the master card, perforations will be provided in the upper row in all of the 32 columns on the control plate. If it is desired to omit on the new card any of the data contained in the field A of the master card, perforations will be omitted in the upper row of the first cycle on the control plate 10 corresponding to those columns on the master card which are to be suppressed. After the data in field A has been transferred to the new card, the master card will be raised so that the field B may be analyzed. The new card will of course be raised also to receive the data in the next position. The control plate 10 will also be raised so that the perforations representing the second cycle will be in position to control the operations. Here again wherever it is desired to omit the transfer of any data contained in field B, to the new card, perforations in the corresponding columns will be omitted in the upper row in the second cycle on the control plate 10; or in other words, wherever it is desired to reproduce the data contained in field B perforations

will be provided in the corresponding columns in the upper row of perforations representing the second cycle on the control plate 10. The manner in which the control plate 10, through the upper row of perforations, controls the reproduction of data is as follows: Referring to Figs. 11 and 21 and assuming that the third control plate counting from the right is to control the machine, the upper row of perforations for the first cycle will be in alignment with the upper row 22a of two rows of sensing pins 22a and 22b. These pins are provided with springs 513 adapted to press them against or through the plate 10.

A restoring bar 514 is adapted to return the pins to normal position. This bar is connected for operation to links 515 (Figs. 10, 12, 18 and 20). These links are connected to arms 516 fixed on a shaft 517. A cam follower arm 518 (Fig. 18) is adapted to cooperate with a cam 519 fixed on the shaft 489. A spring 520 is provided to hold the follower against its cam, the cam and spring thus moving the restoring bar 514 to the right as viewed in Figs. 18 and 21 to permit the pins to take their readings and then to the left to restore them to normal position. Wherever a perforation appears in the upper row on the plate 10 a corresponding pin 22a will advance through the card. This will permit a corresponding feeler 521 (Fig. 21) to rock clockwise under the action of its spring 522 to raise a latching member 523 against the action of its spring 524 into a notch 525 in the lower stop 285. This will prevent the stop from advancing and will permit the corresponding stop bar and type bar to operate under control of the reading taken from the master card. If no perforation appears in this particular position on the control plate 10 the particular pin 22a will not advance and the latch 523 will be held in its lower position, thus permitting the lower bar 285 to advance to prevent operation of the type bar and punch bar. The feeler members 521 are controlled by a restoring bail 526 pivoted on a rod 527. Fixed on the rod 527 is a cam follower arm 528 (Fig. 18) actuated by a cam stud 529 carried on the cam shaft 64. As the shaft turns counterclockwise the rod 527 will be rocked clockwise to the position shown in Fig. 18 to move the bail 526 to the restored position of Fig. 21 restoring the feelers 521 to normal position and permitting the latch 523 to descend to its unlatching position.

The rod 527 will be latched in this position by a spring-pressed latching arm 530 cooperating with an arm 531 fixed on the rod 527. As soon as the pins 22a have taken their reading the cam stud 529 engages the projection 530a on the arm 530 rocking it against the action of its spring to unlatch the arm 531, thus releasing the rod 527. This

permits the bail 526 to move to inoperative position, releasing all of the feelers 521 so that they may rock into cooperation with pins 22a. Thus, pins that have not advanced through the control plate will stop the rotation of the feelers, preventing the corresponding latches 523 from latching the lower bar 285, but wherever a pin 22a has advanced through a perforation in the control plate the corresponding feeler 521 will be permitted to rock, raising the latch 523 to latch the lower bar 285 and permitting the corresponding type bar and punch bar to operate. Across the edges of all of the latches 523 is a latching pawl 532 fixed on a rod 533 (Figs. 21 and 18). Also fixed on this rod is cam follower arm 534 cooperating with a cam 535 on cam shaft 66. A spring 536 holds the follower against the cam. The cam 535 may be timed to move the pawl out of cooperation with the latches 523 during the time that the feelers 521 are taking their readings. The pawl 532 is then released to move into cooperation with the latches to hold those that have been raised in such position and also to hold those that have not been raised in normal position.

Control levers

In addition to the control plate 10, levers 15 (Figs. 18 and 19) may be provided to control the printing of certain data from the master card. The reason for this additional control is that while a plate 10 as shown in Fig. 17 may be properly perforated to control the making of a new card under control of the master card of Fig. 2, a change of address or other data on certain cards may necessitate the suppression of printing of the address or such other data on the new cards. The address and other data will thereafter be applied in the printing perforator machine. According to the table in Fig. 19 one of the control levers 15 is adapted to control the suppression of printing of the data representing the district on the master card. This district is shown printed in line 1 (Fig. 2) as 1324 and is perforated directly below this data in field A. The second lever 15 in Fig. 19 is adapted to control the suppression of the name which appears in line 2 and field B of the master card. The third lever is adapted to control the printing and punching of the state. This is the state that is printed in line 2 and punched in field B2; in the present instance designated as 54. Another lever, the second from the bottom in this instance, is provided to control the printing of the city and state in the address printed in line 6 and punched in field D. The fourth lever from the top controls printing of the debit number printed in line 2 and perforated in field B2 on the master card. The next lever controls the printing of the street appearing in line 4 130

and in field C. The last lever controls the printing and punching of the entire address. Each of the levers 15 is loosely mounted on a rod 537 (Fig. 24) and is connected by pin 5 and slot 538 to a slide 539 mounted in frame 540.

Each of the slides 539 is provided with notches 541. Also carried by frame 540 is a shaft 542 (Fig. 23). Loose on the shaft 542 are several arms 543 reaching over the tops of slides 539. Each arm 543 is provided with a downward projection 544 (Fig. 21) adapted to cooperate with one of the slides 539. A spring 545 is attached to each arm 543 to move the arm downwardly into cooperation with the slides 539. A projection 543a on each arm 543 cooperates with a bail 546 fixed on the shaft 542. A cam follower arm 547 (Fig. 18) also fixed on this shaft cooperates with a cam 548. Several of the arms 543 are provided at their ends with bars 549 reaching across the top of stops 550. These stops are held in their normal up position by springs 551 (Fig. 21) and are adapted to be depressed into the path of a lug 552 carried by each of the sensing pins 22a. This will prevent these particular pins from advancing through the perforations in the plate 10. The corresponding feeler 521 will thus be prevented from operating so that the corresponding stop 285 will advance to prevent operation of the type bar and punch bar. In Fig. 23 the bar 549 associated with the arm 543 farthest to the left reaches over the tops of three of these stops 550. Counting from the right to the left it will be seen that these are the 29th, 30th, and 31st of these stops. These correspond to the 29th, 30th and 31st columns of printed and perforated data on the master card and thus also correspond to the 29th, 30th and 31st columns of sensing pins 22a. There is no stop 550 corresponding to the 32nd column as it is not desired in the present instance to control printing from this column by any of the levers 15. The second lever 543 controls the 28th, 29th and 30th of stops 550 counting from the right to the left in Fig. 23. This controls the debit number data in line 2 and field B2 on the master card.

The third lever 543 in Fig. 23 controls the 26th and 27th stops 550 so as to control the printing of the state in these columns in line 2 and in field B2 on the master card. The fourth arm 543 reaches across the 22nd to the 25th stops 550 inclusive to control the printing of the district number in these particular columns in line 1 and field A on the master card. The fifth arm 543 and the one farthest to the right are both connected to a long bar 549a reaching across all of the stops 550 from the first to the 24th inclusive to control the corresponding columns of data on lines 2, 4 and 6 and fields B, C, D on the master card relating to the address. The 6th and

8th of the arms 543 are connected to a bar 549b which reaches across the same group of stops 550. The 7th and 9th arms 543 are connected to a bar 549c reaching across the 1st to the 21st of the stops 550. The arm 547 is raised and lowered once each cycle of the machine but the arms 543 and their actuating bars 549 will not be permitted to operate during each cycle. These arms are controlled by a notched slide 553. The slide is provided with several notches 554 adapted to cooperate with the arms 543 to permit the latter to move downwardly. A spring 555 (Fig. 25) is connected to the frame 540 and to the slide 553 to move the latter to the left as viewed in Fig. 25. The slide is provided with ratchet teeth 556 and an arm 557 is provided with a spring-pressed pawl 558 adapted to cooperate with the teeth in the slide to move the latter step by step to the right. A spring-pressed latch 559 is adapted to cooperate with the ratchet teeth 556 to hold the slide in the position to which the pawl moves it. The arm 557 is pivoted at 560 and is provided with a spring 561 to rock the arm counterclockwise. A cam follower roller 562 on the arm 557 is adapted to cooperate with a cam 563 (Fig. 18) to move the arm 557 to the right in Fig. 25.

The slide 553 is thus moved one notch to the right during each cycle of operation of the machine. The positions of the notches 554 with respect to the several arms 543 are thus changed each cycle of the machine. Thus, during the first cycle of the machine one of the arms 543 may be permitted to rock downwardly and during the second cycle this arm will be prevented while another one will be permitted to rock. Thus the several bars 549 will be permitted to depress their particular stops 550 in certain cycles of the machine to lock certain of the feeler pins 22a against reading and thus suppress the printing and punching in the corresponding columns.

The levers 15 are loosely mounted on a rod 537. Fixed on this rod are arms 563 and 564 (Figs. 24 and 25). A rod 565 fastened to the arms 563 and 564 reaches across the lower ends of all of the levers 15. The arm 564 also has pin and slot connection 566 with a slide 567 mounted in the frame 540. Thus when any of the levers 15 rocks to the right in Fig. 24 to operative position it will move the rod 565 to the left thus also moving the slide 567 to the left. Slide 567 is provided with a cam edge 568 cooperating with the pin 569 on the pawl 558. Normally the slide holds the pawl out of cooperation with the ratchet teeth 556 so that when all of the levers 15 are in their inoperative position the pawl 558 moves back and forth under control of the cam 563 without actuating the slide 553. When one of the levers 15 is in set position the slide 567 will be in position 13a

to release the pawl 558 so that now as the arm 557 rocks back and forth it will actuate the slide 553 one step for each cycle of the machine.

- 5 When one of the slides 539 is set for operation its notch or notches 541 will be in position under the proper arm or arms 543, but the notches 554 in the slide 553 will not be under the same arm or arms 543. As the slide 10 is shifted one step for each cycle of the machine the notches 554 will reach their position under the proper arm or arms 543 in the cycle in which the slide 539 is to control the operation of the machine. Thus, in this cycle 15 both the notches 541 and notches 554 will be under the same arm or arms 543 so that such arms can move downwardly to depress their stops 550 to cause the type and punch bars to be held down during this cycle of operation. At the end of the series of cycles necessary to punch a new card the control slide 553 will be restored to normal position. 20 This restoration is effected by a cam 570 fixed on shaft 49a (Figs. 14 and 27). The shaft 49a is connected through the crank 109 to the shaft 49 for operation. When the cam rocks the arm 571 clockwise it raises the arm 501 (Fig. 27) rocking the latter arm counterclockwise about its pivot 478 (Fig. 25). When this operation takes place the arm 504 is permitted to rise by reason of its pin and slot connection with arm 505 as shown in Fig. 22. This movement pulls the link 572 downwardly (Figs. 25, 26, 18). 30 The link is shown broken in Figs. 25, 26, but is, complete in Fig. 18. The link 572 is guided by pins 573 (Fig. 25) attached to the frame 540. A pin 574 fixed in the latching member 559 (Fig. 25) reaches through a hole in the link 572 so that when the link is depressed it will pull the latching member 559 out of cooperation with the slide 553. A lateral projection 574a at the top of the link 572 is adapted to depress the pawl 558 out of cooperation with the ratchet teeth 556. The slide 553 will thus be free and will be pulled by its spring 555 to the left as viewed in Fig. 25, back to its normal position. 40 A stop shoulder 575 on the slide 553 is adapted to engage the frame 540 when the slide reaches its normal position.

The machine will then commence another series of cycles and as long as the particular lever 15 is set each series of cycles will be a repetition of the previous series. The setting of the levers 15 as we have seen controls only the suppression of selected ones of the type and punch bars.

50 Other controls used in the making of new cards are effected through perforations in the control plate 10 in any of the several positions in the lower row of perforation positions in each of the cycles on the right hand side of the plate. In Fig. 17 plate 10 is

shown with a few scattered perforations on this side of the plate. During the successive cycles of operation of the machine the pins 22b, (Figs. 11 and 21) will press against the lower row of hole positions in the plate and wherever a perforation appears the corresponding pin 22b will move forward during that particular cycle of operation. After the pins take their readings the restoring bar 526 (Fig. 21) releases the feelers 521 and also releases a lower set of feelers 576. Where a pin 22b has advanced the corresponding feeler 576 will be permitted to rock counterclockwise about the rod or shaft 527 to the position in which the feeler 576a is shown in Fig. 37. The feeler 576 (Fig. 21) will then be permitted to rock under the actuation of its spring 577 moving its follower roller 578 into cooperation with a corresponding cam 579. The lower end of the feeler arm 576 is provided with a flange 580 adapted to cooperate with a hook 581. The spring 577 is connected between the feeler and the hook so that when the feeler moves to the right the hook springs up past the flange 580. During the proper time in the cycle of the machine the cam 579 will move the feeler arm 576 to the left, moving the hook 581 in the same direction. The hook 581 is connected to an arm 582 fixed on a rod or shaft.

There are several of these shafts all of which are connected to hooks 581 each of which is associated with one of the feeler arms 576. If a perforation appears in the control plate in the lower row of the first cycle and in the column designated "New card drop" (Fig. 16) the corresponding pin 22b will operate in the first cycle and its feeler 576 will cooperate with the hook 581 connected to the shaft 267 of Fig. 21. When this shaft is rocked counterclockwise in Figs. 21 and 18 it will pull the link 265 toward the right. In Fig. 62 it will be seen that this will rock the latching pawls 261 out of cooperation with the card supporting frame 232 previously described, to permit the frame to drop with the new card to move the card from the position N1 to the position N3 of Fig. 61 for the purpose previously shown.

Reaching across the tops of all of the hooks 581 is a bail 583 fixed on a shaft 584 (Figs. 21, 18). A cam follower arm 585 fixed on this shaft cooperates with a cam 586 on the shaft 64. At the end of the cycle the cam rocks the bail downwardly releasing any of the latches 581 that may be in cooperation with feelers 576. Springs 586a (Fig. 18) connected to arms 587 fixed on shaft 267 and the other shafts in this group will then rock the shafts back to normal position.

Some of the feelers such as those designated 576a (Figs. 21 and 37) cooperate with

links 581a connected to arms 582. The links 581a are connected to the feelers 576a by springs 577 and are provided with flanges 581b. When the feeler 576a is in normal position as in Fig. 21 it holds the links 581a in its lower position with the flange 581b in the dotted position shown in Fig. 37. As the cam 579a turns, it will normally move the arm 576b to the left against the action of its spring 576c without moving the link 581a. When the corresponding sensing pin 22b senses a perforation and advance as in Fig. 37 and when the feeler 576a moves to the right it will permit the link 581a to rise into the path of the arm 576b. Now when the cam moves the arm 576b to the left as indicated by the dotted line position as in Fig. 37, it will move the link 581a to the position there shown to rock a shaft 428 or any other shaft as the case may be. Where it is desired to have the cam hold the shaft 428 in set position a sufficient length of time to permit certain operations to take place the long radius of the cam may be of considerable circumference as shown in Fig. 37.

Punching a letter without printing

In Fig. 2 line 1 the letter A is shown printed in the middle of the line. This letter is normally printed when the card form is made on the printing press. No corresponding perforation in the field is made at that time. When the card is later inserted in a punching machine to print and punch the various data, the perforations corresponding to this letter A or any other letter in this position are made on the punching machine, the operator at this time suppressing the printing of the letter on the card. When a new card is being made out on the present machine under control of the card of Fig. 2 the new card also has this or some other letter printed in this position. The machine is therefore set to omit the printing of this letter on the new card but is permitted to enter the perforations corresponding to the letter. To permit punching while suppressing printing, the hammer which operates the printing type will be locked against operation. In Fig. 16 the perforation which controls this printing will be in the column designated A and C NON PRINT. Perforation will be in this column in the first cycle since the reading and punching under control of the first line takes place during that cycle.

A perforation in this position causes the shaft 596 (Figs. 12 and 18) to rock. This moves the link 597 to the right. The left end of the link 597 is connected to an arm 598 fixed on a shaft 599 on which is also fixed a latching pawl 600 (see also Fig. 60). This pawl is adapted to be rocked into a notch 601 in the link 375 associated with the type bar which carries the type for printing in

the 16th column in which this letter is printed. Now when the punch bar and type bar rise to control printing and punching the arm 377 (Fig. 60) is not rocked by the spring 380 so that when the arm 372 moves the hammer in question will not be released to effect printing although the type bar has been set in position for printing. While the printing has thus been suppressed, punching under the control of the punch bar which has also been set takes place in the usual manner.

Month and day, open item and O. H. L. reading

Referring to Fig. 2 the perforations in the sub-fields 26 and 26a of the horizontal fields F and G are divided into three groups. One group represents the perforation 25 which indicates that a bill or notice has been sent, and may be termed an open item. Another group is the perforations in the sub-field 26 or 26a without the small square containing the perforation 25. These perforations represent the month and day printed in the sub-field 27 in lines 9 and 10. The third group is the perforation or perforations in the squares containing the letters OH&L. A perforation may appear in any one of these three positions. Three cycles of operation of the machine are required to read the perforations in the field F and three more cycles to read the perforations in the field G.

In the first of these cycles the perforations representing the month and day are read and the proper entries made on the new card. During this cycle reading of the perforation 25 representing the open item and the perforation 28 in the OH&L position are both suppressed. During the second cycle the reading of the perforations representing the month and day and the perforation in the OH&L position are suppressed, permitting the reading of the open item perforation 25. During the third cycle the reading of the open item perforation and the month and day perforations are suppressed while the reading of the OH&L perforations are permitted. The control plate 10 of Fig. 17 contains perforations for controlling the making of a card 11 shown in Fig. 4. On this card the month and day having been read are printed in the several sub-fields 602. No corresponding perforations are made on this card. The several sub-fields 603 have a cipher printed therein indicating that a perforation was found in the corresponding open item position at 25 on the card of Fig. 2. In the OH&L squares 604 a perforation was found in the H position in several of the fields on the card of Fig. 2. The pin which reads this position is the second pin from the bottom, of the 6 pins in each column of pins. According to the table in Fig. 3 a perforation in this position controls the setting of a type bar to print an oblique line. Thus

in Fig. 4 this oblique line is shown printed over the H in the several positions corresponding to the positions containing perforations in Fig. 2. In Fig. 17 the three readings taken in the field F of the master card are effected during the 9th, 10th and 11th cycles.

In the 9th cycle two perforations are shown corresponding to the columns designated in Fig. 16 "suppress OHL pins" and "suppress open item pins". Thus during this cycle the day and month pins are permitted to operate. In the tenth cycle two perforations, in the month and day and in the OHL columns are shown thus permitting the open item pins to operate. In the 11th cycle perforations are shown in the month and day and in the open item columns thus permitting the OH&L pins to operate. It should be borne in mind that during these three cycles the master card is held in the one position but that the control plate 10 is shifted one step upwardly for each cycle. After completion of the 9th, 10th and 11th cycles the master card is then shifted so that the pins will read in the G field in the master card and the plate 10 is raised so that the perforations for the 12th cycle will be in controlling position. The perforations in the month and day, the open item and the OHL positions on the control plate 10 for the 9th, 10th and 11th cycles are repeated for the 12th, 13th and 14th cycles so that the same operations take place for the reading of the perforations in the field G. The data taken from this field is entered on the card 11 of Fig. 4 in the several squares or fields 602a, 603a, and 604a. For suppressing the reading of the month and day perforations in field 26 of the master card means are provided for preventing the particular sensing pins 22 from reading a card. In Figs. 11, 29 and 51 the pins which read in this field 26 are shown as having collars 605 fixed thereon. A slotted plate 606 reaches up through the pins and cooperates with the collars. In the position of Fig. 51 the plate 606 is adapted to prevent the pins which read the month and day, from reaching through the card but does not prevent the pins which read the open item perforations or the OH&L perforations from operating.

The plate 606 is attached at its opposite ends to blocks 607 (Fig. 52) adapted to slide in slots 608 in the frame 609. Springs 610 connected at one end to pins 611 on the blocks 607 and at their other ends to the frame 609 are adapted to move the plate 606 toward the right to permit the month and day pins to take their readings. A pair of arms 612 (Fig. 51) connected to the pin restoring member 274 reach back and engage the opposite ends of the plate 606. When the member 274 moves to the right it releases the plate 606 so that the springs 610 can move it to the

right if it is free to move in this direction. When the member 274 moves to the left to restore the pins 22 it moves the plate 606 back to normal position. In order to suppress the operation of the month and day reading pins, sliding links 613 (Fig. 52) are provided. There may be two of these links, one at each end slideable up and down on pins 614 fixed to the frame member 609. Both of the slides may be connected to arms 615 fixed on a shaft 616 so that the up and down movement of one of the slides will cause similar movement of the other. As shown in Fig. 52 each slide 613 is provided with notch 617 adapted when the slides are in their upper position to lie in the path of movement of the pins 611. This will permit the plate 606 to move to the right to permit the month and day pins to operate. If the slides 613 are moved to their lower position they will prevent the plate 606 from moving to the right and thus prevent the month and day pins from operating. The extension 613a of one of the links 613 is connected to the shaft 618 (Fig. 12). The rocking of this shaft under control of the perforation in the plate 10 thus controls the position of the slides 613 to determine whether the plate 606 shall move to the right or not.

The pins 22 which read the open item perforation indicating whether or not a notice or bill has been sent to the customer are provided with an upward extension 283a (Figs. 51 and 29). In Fig. 29 it will be seen counting from the right the first pin 22 has a block 283 without the upper projection 283a. The second pin and thereafter every third pin is provided with an upward projection 283a. Looking at the card in Fig. 2 and counting from the left it will be seen that the second vertical row of pins and every third row thereafter is adapted to align with one of the open item or notice sent perforation positions 25. Only the uppermost pin in these particular columns is used to sense these perforations. Reaching across all of the pins 22 is a plate or bail 619 pivoted at 620 (Figs. 29 and 51). When lowered into the position of Fig. 51 this bail is adapted to lie across the path of all of the projections 283a. These particular pins do not have the collars 605 and are therefore not under the control of the plate 606 but are controlled by the restoring plate 274. When the member 274 moves to the right these open item pins will take their readings if the bail 619 is raised but will be locked out if the bail is in the position of Fig. 51. To operate the bail an arm 621 is fixed on the shaft 620 (Fig. 52) and is connected by a link 622 to an arm 623 fixed on the shaft 624 in Fig. 18. This shaft is controlled as disclosed in connection with Fig. 21 by the proper perforation in the control plate 10.

The suppression of the readings taken by

the OH&L pins is effected by suppressing the operation of the comb 281b (Fig. 54) which is controlled by the two lower pins so that the reading taken by the next to the lowest 5 pin will have no effect in controlling the operation of the machine. Each of the combs 281b is provided with a projection 625 reaching downwardly as shown in Figs. 11 and 54. Below all of these projections is a bail 626 10 pivoted at 627. In the position of Figs. 11 and 54 the combs 281b are free to descend under control of the readings taken by the two lower pins. When it is desired to suppress the effect of the reading taken by these 15 pins the bail is rocked counterclockwise in Fig. 11 so that when the several combs 281 are lowered all of the combs 281b will be held up. The shaft 627 has fixed thereon an arm 628 (Fig. 18) resting between two arms 629 20 loose on the shaft 627. A spring 630 holds the arms 629 against the arm 628. An arm 631 also loose on the shaft 627 is provided with a pin 632 reaching between the arms 629. The lower end of the arm 631 is connected to a link 633 which is connected at its other end to an arm 634 fixed on the control shaft 635. The rocking of the shaft 635 is controlled by the proper perforation in the plate 10 as described in connection with Fig. 25 30. When the shaft 635 is rocked, moving the link 633, the arm 631 will be rocked counterclockwise in Fig. 18 moving one arm 629 to the left. The spring 630 will cause the other arm 629 to tend to follow thus rocking 35 the arm 628 and with it the shaft 627 on which the bail 626 is fastened. This will rock the bail into position to hold up the combs 281b. will operate without operating the link 394. Connected to this link is a link 636 reaching downwardly and connected to an arm 637 on a shaft 638 on which is also fixed an arm 639. Connected to the latter arm is a link 640 (see also Fig. 20) connected to an arm 641 on the control shaft 642. This shaft is actuated by the hooks and the cams on the shaft 64 (Fig. 21) under control of the feelers 576 as heretofore described. The perforation in the control plate 10 for controlling the suppression of printing will be in the column designated NON PRINT. A perforation in all of the positions in this column will suppress printing during all of the cycles while a perforation in certain cycles only will suppress printing in those cycles alone.

Control of card shifting clutches. The master card vertical clutch

In Figs. 19 and 33 it has been seen that the gear 157 is constantly turning and thus the clutch member 156 is also constantly in operation. To raise the card supporting frame the clutch member 155 is moved into mesh with the member 156. To accomplish this the member 155 is provided with a circumferential groove into which rollers 643 reach. These rollers are carried on arms 644 fixed on a shaft 645 (see also Fig. 35). A spring 646 (Fig. 36) tends to press the clutch member 155 into mesh with the member 156 but a latch 647 cooperating with a projection on one of the arms 644 holds the parts in de-clutched position. The latch 647 is pivoted at 648 and is held by a spring 649 in its operative position. A link 650 connected to the latch 647 (Figs. 33, 36) is connected to an arm 651 on the control shaft 652. The shaft 652 has two of the arms 582 (Fig. 21) fixed thereon. A rod 653 connected between the ends of these arms has attached to it eight of the latching hooks 581 (Figs. 21 and 38). The operation of each of these hooks is controlled by a different one of the feelers 576 which in turn is controlled from a different one of the pins 22b. A perforation in the control plate permitting the operation of a particular one of the pins 22b will cause the corresponding feeler to operate. The corresponding cam 579 will then move the feeler and with it the corresponding hook 581 to rock the shaft 652. As shown in Fig. 41 the cams are arranged in progressive order so that each one comes into operative position with respect to follower 578 of Fig. 21 at a different time in the cycle of the machine. The reason for this difference in the timing is to effect the raising of the master or control card different distances. The throwing out of the operating clutch takes place at a definite time in the cycle of operation so that the time at which the clutch is thrown in will determine the dis-

5 tance through which the card and its frame are raised before declutching takes place. In the present instance eight cams 579 are shown in Fig. 41 so that movement of the frame through eight different distances may be effected by selectively bringing into control any one of the eight cams. Referring to Fig. 16 the perforations in the control plate 10 which determine the selection of 10 the cam are those shown in the lower one of the two horizontal rows of perforations for each cycle from the fourth to the eleventh columns inclusive. Where the card is to be raised during any cycle a perforation in one 15 of the eight positions will be provided. The position of this perforation depends upon how far it is desired to raise the card during that cycle. The perforation will cause the operation of one of the eight hooks 581 (Figs. 20 21 and 38). The corresponding one of the cams 579 will cause the shaft 650 to rock. This shaft will then operate the link 652 (Figs. 20 and 33) moving the latch 647 out 25 of cooperation with the arm 644. The spring 646 will then move the clutch member 155 into mesh with the member 156. The gears 153 and 153' will then commence to rotate and through the racks 152, 152' will commence to raise the frame 151 and with it the 30 frame 145 (see Fig. 28). As the parts rotate a disk 654 provided with a cam portion 655 and which is constantly running, engages a projection 656 on one of the arms 644 (see Fig. 33), thus rocking the arms 644 35 and moving the clutch member 155 out of mesh with the member 156. The latch 647 then latches the parts in this position. The upward movement of the card supporting frame stops at this moment.

40 In order to prevent overthrow of the cam member 155 the spring-actuated pawl 657 is provided to cooperate with teeth 658 on the cam member 155. When the clutch is in mesh the pawl 657 is out of cooperation with the 45 clutch member 155 but when the latter member is thrown out of mesh the teeth 658 move into cooperation with the latching pawl which then arrest the rotation of the member 155. In order that the clutch member 155 may be 50 constrained to turn with the shaft 154 and at the same time be free to move along this shaft into and out of mesh with the member 156, a two part or split collar 659 is provided. One of these parts is fixed to the member 155 and 55 the other to the shaft 154 and the two parts have sliding engagement with each other at 660. The control card in its frame may thus be raised during any of the several cycles required to produce a new card and may be 60 raised during each of such cycles a distance depending upon which of the eight possible positions in the control plate is provided with a perforation. Whenever the frame is raised it will be held in position by a latching pawl 65 62a cooperating with a ratchet wheel 162b

fixed on the shaft 154 (Figs. 33, 35, 36). After the several cycles of operation have been completed the card frame will be dropped to its starting position by moving the latching pawl 162a out of mesh with its ratchet. For 70 this purpose the pawl is pivoted at 661 as shown in Fig. 35 and is connected by a link 662 to an arm 663 (Figs. 33 and 35) fixed on the control shaft 664 (see also Fig. 21). This control shaft is operated under control 75 of one of the feelers 576a which in turn is controlled by the pin 22b adapted to read a perforation in the second column counting from the right in the control plate 10 of Fig. 16 which column is designated "master card 80 horizontal carriage return".

There will of course be only one perforation in this column and it will be located in the next cycle after the completion of the making of the new card. The card frame will then drop to normal position under control of the governor as previously described. Means may be provided to prevent breakage of any of the parts of the machine in the event that the clutch member 155 has not been disengaged from the member 156 when the carriage 151 reaches the end of its upward movement. This means may comprise an arm 665 (Figs. 33, 35 and 36) pivoted at 666 and provided with a projection 667 adapted to cooperate with an arm 668 fixed on the shaft 645 with the arms 644. The card frame 151 (Fig. 36) is provided with a pin 669 adapted when the frame nears the upper limit of its movement or has passed beyond its last operative position, to engage the arm 665 thus rocking the arm and also rocking the arms 644 to demesh the clutch member 155 from the member 156. The latch 647 will then latch the parts in this 90 position.

Master card horizontal clutch

In Figs. 10, 19 and 28 we have seen that the shaft 174 is constantly turning and with it the clutch member 173. The clutch member 172 is normally held out of mesh with the member 173, against the action of spring 670 (Fig. 47) by a latch 671 cooperating with one of the arms 672 provided with pins 673 reaching into the circumferential groove in member 172. The latch 671 is connected by a link 674 (Figs. 47 and 20) to an arm 675 on the control shaft 676. When the shaft 676 is rocked it will move the latch 671 out of cooperation with the arm 672 and the spring 670 will move the clutch member 172 into mesh with the member 173. This will cause the clutch members to operate, turning the gear 171 and moving the rack 170 connected to the upper frame 145, toward the right as viewed in Figs. 28 and 29.

The split sleeve 677 permits the relative movement of the clutch member 172 into mesh with the member 173 while constraining the member 172 to rotate the gear 171.

125

130

Fixed with respect to the clutch member 173 (Fig. 47) is a disk 678 having a cam portion 679 adapted when it engages the cam portion 680 of the arm 672 to rock the arm 6 and thus move the clutch member 172 out of mesh with the member 173. The latch 671 will then cooperate with the arm 672 and hold the parts in declutched position. When the card frame 145 is moved to the 10 right the spring in the spring drum 179 (Figs. 28 and 29) will be tensioned so as to store energy by which the frame may be returned to its normal position to the left at the end of the operations. When the clutch 15 parts are demeshed the latching pawl 681 (Fig. 29) will cooperate with the teeth 682 (Fig. 47) of the clutch member 172 to prevent overthrow. A latch 181 (Figs. 29 and 47) cooperates with the ratchet 180 to hold 20 the card frame in the position to which it has been moved. When the clutch is thrown in to move the carriage to one side, the distance through which it is moved may vary. In the present instance it is adapted to be 25 moved through any of five different distances. In Fig. 16 perforations in the lower row of each cycle of control perforations in the control plate 10 in columns 14 to 18 inclusive are adapted to control the distances 30 of movement of the card frame. When the frame is to be shifted laterally during a particular cycle of operation of the machine a perforation in that cycle in one of the five columns will be provided. That particular 35 perforation through its sensing pin 22b (Fig. 21) will then call into operation its particular feeler 576 to be actuated by one of the five cams 579 shown in Fig. 40. This is the second group of cams counting from 40 the left in Fig. 38.

The cams as shown in Fig. 40 are arranged in progressive order so as to operate their feeders 576 and hooks 581 at different times in the cycle of operation. The 45 cam 679 will then demesh the clutch at the usual time and the card frame will have moved a distance dependent upon where the control perforation is located on the control plate. After the making of the new card 50 has been completed the frame will be returned to its normal position by lifting the latching pawl 181 (Figs. 29 and 47) out of the ratchet 180. Back of the rear end 181a of the latching pawl is one arm of a bell 55 crank 684 pivoted at 685 and connected by a link 686 (Figs. 29 and 47) to an arm 687 (Fig. 20) on the control shaft 688 (Fig. 21). This shaft is controlled by a perforation in the second column from the right in the 60 control plate 10 of Fig. 16. This column is designated as the master card horizontal carriage return. There will of course be one perforation in this column and it will be 65 located in the cycle following the last cycle used to make up the new card. When the

latching pawl 181 is lifted the carriage will be returned by the spring drum 179 as previously described. In the event that the clutch members may not have been de-clutched before the carriage reaches the end 70 of its travel the carriage is adapted to strike a bell crank 689 (Figs. 28 and 29) thus raising link 690 connected to an arm 691 fixed on the side of one of the arms 672. This will rock the arms 672 to lift the clutch member 172 out of mesh with the member 173. It is of course understood that both the vertical and horizontal movements of the card carriage or frame may take place simultaneously and that the returning of the carriage in both of these directions may also be accomplished at the same time. 75 80

Notice card vertical clutch

In Figs. 15, 19 and 61 we have seen that the driving shaft 254b is constantly running. Through the bevelled gears 254-254a and sleeve 253 a clutch member 252 is also constantly running. The clutch member 251 is normally held out of mesh with member 252 by a latch 692 cooperating with one of arms 693 having studs 694 reaching into the circumferential groove 695. Latch 692 is held in position by a spring 696 and is pivoted at 697. A link 698 having a flange 699 is pivotally attached to the latch 692 at 700. This link is connected at its other end on arms 701 (Figs. 10 and 20) pivoted at 702 and fixed with respect to arm 703. The latter arm has pin and slot connection at 704 with an arm 705 fixed on shaft 706. The rocking of shaft 706 will move the link 698 to rock the latch 692 out of engagement with arm 693. The clutch spring 707 will then move the clutch member 251 into mesh with the member 252. A split sleeve 708 will maintain driving connection between the clutch member 251 and the gear 255 fixed on the shaft 250 which carries gears 249 meshing with racks 248 on the card supporting frame 232. Thus the card frame will be raised until the clutch is demeshed. This demeshing takes place as soon as the cam face 709 on the disk 710 strikes the cam face 693a on one of the arms 693. The clutch will then be latched in operative position by the latch 692. The card supporting frame or carriage will be latched in the position to which it has been raised by the latching pawl 256 in cooperation with the ratchet 255. The shaft 706 (Fig. 20) is provided with two of the arms 282 as shown in Fig. 38 and the interconnecting rod 711 carries twelve of the hook members 581. Each of these members is adapted to cooperate 100 with one of the twelve cams 579 shown in the group of cams farthest to the left on shaft 64 of Fig. 38 and also shown in Fig. 39. 105 110 115 120 125

In Fig. 39 the cams are shown as differentially positioned so as to actuate their respective hook members 581 at different times in 130

the cycle of operation of the machine so that the card carriage may be lifted a different distance before the clutch is demeshed. Thus, as in connection with the vertical and 5 horizontal movements of the master card carriage, the new card carriage may be lifted any of twelve different distances depending upon which of the twelve hook members 581 is selected to rock the shaft 706. According 10 to Fig. 16 the twelve perforation positions in the lower row of columns 21 to 32 inclusive in each cycle of the machine are employed to control the rocking of the shaft 706. When it is desired to raise the card a definite distance 15 during a particular cycle, one of these perforation positions will be punched so as to control the clutch at the beginning of the cycle to raise the card the desired distance. When the clutch member 251 is cammed out of mesh 20 with member 252 the teeth 712 (Fig. 15) will engage a latching pawl 713 to prevent overthrow of the parts. After the new card has been completed the card carriage will be dropped back to normal position by raising 25 the pawl 256 out of mesh with the ratchet 255 as shown in Fig. 10. The latching pawl 256 is connected to a link 714, which as shown in Fig. 20 is connected at its other end to arm 715 on the control shaft 716. The shaft 30 30 (Fig. 21) is controlled by the sensing pin 22b by a control perforation in the plate 10 in the ninth column counting from the right (Fig. 16). This column is designated "new card vertical return". There will, of course, 35 be only one perforation in this column and it will be located in the cycle following the last one used in making out the new card.

As previously described in connection with Fig. 61 a spring drum 257 may be provided 40 to aid in lowering the card frame and a governor 260 will control the rate of speed at which the card frame descends. To prevent breakage of any of the parts of the machine in the event that the clutch may not 45 have been properly demeshed before the frame reaches its upper limit, a pin 717 (Fig. 61) is provided on the card frame and is adapted to rock an arm 718 connected to an arm 718a fixed on shaft 719. Also fixed 50 on this shaft is an arm 720 (see also Fig. 15) connected by a link 721 to an arm 722. The latter arm is fixed on the shaft 723 on which the arms 693 are fixed. Thus, when the pin 717 rocks the arm 718 the arms 693 will also 55 be rocked to move the clutch member 251 out of mesh with the member 252. The latch 692 will then latch the clutch in demeshed position.

60 Automatic starting of card feed shuttles

After the making of a new card under the control of a master card has been completed, the card carrying frames will be restored to their normal positions as described and the 65 card feeding mechanisms including the card

shuttles will then be brought into operation to feed out the control card and also the new card and to feed in the next control card and another new card in blank form ready to be perforated and printed upon. These several operations are performed in the next cycle following the last cycle used in making out a new card. In Fig. 17, for instance, 15 cycles of the machine are used as indicated by the control plate 10 to make out the card shown in Fig. 4. The perforation 724 in the 16th cycle causes the restoration of the new card supporting frame. The perforation 725 brings about the restoration of the master card downwardly. The master card does not move horizontally in making out the new card in Fig. 4 and therefore there is no horizontal restoration in the present instance.

The next perforation 726 causes the institution of a card feeding operation. This 85 perforation through its sensing pin 22b (Fig. 21) causes the rocking of the control shaft 727. Fixed on this shaft is a bevelled pinion 728 (Fig. 18) meshing with a bevelled pinion 729 fixed on a shaft 730 carrying an arm 731. A link 732 connected to this arm is provided 90 with a notch 733 (Figs. 43 and 48) adapted to cooperate with a pin 734 on an arm 735. A spring 736 is adapted to normally hold the link 732 in cooperation with the pin 734. Thus, when the shaft 730 is rocked clockwise as viewed in Figs. 43 and 48, it will 95 rock the arm 735 clockwise about its pivot 737. This will raise the finger 735a to permit the link 81 to rise under the influence of its spring 91 as seen in Fig. 44. This will bring the pin 80 in position to be engaged by the hook 85 so that when the hook moves to the left it will move the link 81, rocking the clutch stop member 53 out of engagement 100 with the clutch dog 43 thus instituting a card feeding operation as previously described. This causes the master card and the new perforated card to be fed out of the machine and another set of cards to be moved into 105 operative positions.

During a card feeding cycle the machine clutch which causes operation of the operating cam shafts must be thrown out to suppress the operation of these shafts during 115 the card feeding cycle. This is effected as shown in Figs. 43 and 48 by a finger 738 reaching over the top of the link 81a. Arm 735 is provided with a projection 739 reaching over the top of the finger 738. When the arm 735 is rocked clockwise it presses the finger 738 downwardly, thus moving the link 81a downwardly. This moves the pin 80a 120 out of cooperation with the hook 85a.

The clutch stop 58 (Fig. 46) will thus remain in position to intercept the clutch dog 51 to disengage the machine clutch and stop the rotation of the cam shafts. When the finger 738 is rocked downwardly it will be 125 locked in position by a latch 740 cooperat- 130

ing with a flange 741 on the extension 738a of the finger 738. After the card feeding cycle has been instituted the clutch stop member 53 may then be released so as to stop 5 the operation of the shuttles at the end of the cycle. For this purpose the cam 742 is provided on the shaft 49a (Fig. 43). This cam is adapted to engage the follower 743 on an arm 744 pivoted at 745. This arm is 10 provided with a cam surface 746 adapted to engage a pin 747 on the end of link 732 to cam the link out of cooperation with the pin 734. A spring 748 will then rock the arm 735 counterclockwise to lower the pin 80 15 out of cooperation with the hook 85. The stop member 53 (Fig. 44) having rocked into stopping position will thus remain there so that the shuttle operating clutch will be thrown out and the card feeding operations 20 will cease. At the proper time during the card feeding cycle the parts will be operated to institute a series of machine cycles for the making out of a new card. For this purpose a crank 749 on the shaft 49a (Fig. 25 43) will engage the rear end 740a of the latch 740 rocking the latter out of cooperation with the finger 738 thus permitting the link 81a to move upwardly to cooperate with the hook 85a to rock the clutch stop member 58 (Fig. 30 46) out of cooperation with the clutch dog 51 thus permitting the clutching in of the machine clutch.

The link 81a will now remain in the upper position to be actuated by the hook 85a 35 during each cycle of operation of the machine so as to permit the clutch to continue in operative position for successive cycles during the making of a new card. Before a new series of cycles is commenced it is necessary 40 that the control plate 10 of Fig. 17 be restored to its starting position. This is accomplished by a cam 570 on the shaft 49a (Figs. 27 and 14). This cam at the proper time during the card feeding cycle rocks 45 the arm 571 thus rocking the arm 501 (Fig. 26) to move the pawls 480 and 482 out of cooperation with the ratchet 479. The frame 465 supporting the plate 10 will then descend as heretofore described, under control 50 of the governor 496 (Fig. 18). The frame will descend to the point where the stud 472 of Fig. 22 rests on the cam 471. In this position the horizontal rows of perforations in the upper part of the plate representing the 55 first cycle will be slightly below the perforations 467 in the plate 468 through which the sensing pins 22a, 22b operate to take their readings. The frame with the plate will be raised into reading position during the early 60 part of the first machine cycle, in time for the operation of the pins 22a and 22b.

Operation of shuttles is controlled by position of the card frames

65 It is necessary in order to feed cards into

and out of the card supporting frames that the frames be in their normal positions. Means are therefore provided to prevent a card feeding cycle of the machine unless these frames are in their normal positions. This means includes a latch 750 (Fig. 43) 70 pivoted at 751 and cooperating with the link 81 to hold it out of cooperation with the hook member 85. Thus the latch will not throw out the clutch stop member 53 of Fig. 44 75 to permit the clutch to operate the card feeding mechanism.

The latch 750 is connected by a link 752 to an arm 753 fixed on a shaft 754. The shaft 754 is provided with a bevelled gear 755 meshing with the bevelled gear 756 fixed on shaft 757. Also fixed on this shaft is a feeler finger 758 adapted to press against the card frame 151 and to reach through a hole 759 in the frame when the latter is in its restored position. Also fixed on shaft 757 is an arm 760 (Fig. 18) connected by a link 761 to an arm 762 (Figs. 12 and 61) fixed on a shaft 763. A link 764 has pin and slot connection with the arm 762 and link 761 and is also connected therewith by a spring 765. Link 764 is provided with a cam follower 766 adapted to cooperate with the cam 767 on the shaft 64. When the link 764 is moved to the left in Fig. 12 it will tend to pull the link 761 to the left and also rock the shaft 763 counterclockwise. If the parts do not move a spring 765 will yield. Shaft 763 is provided with a feeler finger 768 adapted to press against the new card frame 232 and to reach through a hole 769 in this frame when the latter is in its normal position. In Fig. 61 the frame is shown below its normal position so that the finger cannot reach through the hole 769 and thus the shaft 763 and link 761 cannot be moved by the link 764 of Fig. 12. This also prevents the rocking of the shafts 757 of Fig. 18 so that although the master or control card frame 151 is in its normal position the finger 758 will not rock into the hole in the latter frame. This will also prevent the shaft 754 from rocking and the latch member 750 of Fig. 43 will remain over the link 81 to prevent card feeding. So far we have seen if the new card frame is not in its proper position the card feeding shuttles will not operate. Also if the master control card frame is not lowered to its normal position the shuttles will be prevented from operating. 110 115 120 125

A third finger 770 (Figs. 10 and 28) is connected by a link 771 (see also Fig. 20) to an arm 772 fixed on the shaft 757. When the side moving card frame 145 is in the position of Fig. 28 the feeler finger 770 will be free to move across the path of the frame but when the frame has been moved toward the right the finger will be prevented from rocking. When the link 764 (Fig. 12) operates and tends to rock the shaft 757 of Fig. 18 it will 130

thus also tend to rock the finger 770 and if the latter finger is prevented from rocking it will prevent the shaft 757 from rocking. This, in turn will prevent the latch 750 from being moved away from the link 81. It will be seen from this when the hook member 85 of Fig. 44 moves to the left for a card feeding operation it will not cooperate with the pin 80 on the link 81 and will not cause the card feeding clutch to operate. If, on the other hand the card supporting frames are all in their normal positions, the several feeler fingers will all rock when the link 764 of Fig. 12 moves to the left and this will result in the 15 rocking of shaft 754 of Fig. 43, moving the link 752 to the right to remove the latch 750 from over the link 81. This will permit the link to rise so that the pin 80 will be actuated by the hook 85 to cause the card feed clutch 20 to operate.

Also fixed on the shaft 754 (Fig. 22) is a latching arm 773. This arm cooperates with an extension 505a of the arm 505. In the position shown it is impossible to operate 25 the crank 469 to lower the control plate frame 465 from the position of Fig. 22. When the card holding frames are in normal positions and the three feeler fingers all operate and cause the rocking of shaft 754, the latching 30 arm 773 will be lowered out of cooperation with the arm 505a. Thus only when the card frames are all in their normal positions can the control plate frame 465 be moved below the position of Fig. 22.

35 One of the reasons for this interlocking is to prevent the changing of a control plate while the machine is in the midst of an operation making out a new card or in the event that the machine may have stopped in the 40 midst of such an operation.

Non-jam control

In order to prevent damage to cards due 45 to failure of a card to feed to position, means are provided to detect the absence of a card from its position and to cause the machine to stop when a card fails to feed to its operative position. In my Patent #1,506,382 dated August 26, 1924, I disclose a non-jam control device associated with the card feed clips. When the clips closed upon the card and as long as the card remained in the clips, the machine was permitted to continue to 55 operate, but where the clips failed to receive a card or where during the feeding operation the card slipped out from the clips an arm was permitted to rock into latching engagement with a link. At the end of the 60 feeding stroke this link engaged and rocked a lever which through intermediate connections brought about stoppage of the machine. In Fig. 7, I have shown a similar link 774, which, when the card shuttle or carriage 65 reaches the left hand end of its stroke, will

rock a bell crank arm 775. The manner in which the link 774 is controlled by the card clips is not disclosed in detail in the present application since it is fully disclosed in the aforesaid patent. The bell crank 775 is connected to a link 776 which has pin and slot connection with an arm 777 fixed on shaft 778. This shaft is also shown in Fig. 43. A similar device is shown in connection with the new card shuttle in Fig. 8. Here a link 779 is controlled by the card feed clips and is adapted, when the shuttle reaches the end of its travel to the left, to rock an arm 780.

The arm 780 is divided at 781 and is fixed with respect to an arm 782 connected to a link 783 having pin and slot connection with an arm 784 also fixed on the shaft 778. In Fig. 43 shaft 778 is shown as having fixed thereon an arm 784 to which is attached a spring 785 tending to hold the shaft 778 rocked in a counterclockwise direction. If either of the links 776 or 783 is actuated by reason of the absence of a card in the master card shuttle clips or the new card shuttle clips the raising of these links will rock the shaft 778 clockwise against the action of spring 785 and through the arm 786 will pull the link 787 to the left. This link is connected at its right end to one arm 788a of a finger 788. As seen in Figs. 43 and 49, finger 788 is pivoted at 789 and when the link 787 moves to the left it will rock the finger downwardly, depressing the link 81a to the position of Fig. 49 where it cannot be actuated by the hook 85a. The clockwise rotation of finger 788 is adapted to rock another finger 790 in a counterclockwise direction to depress the link 81 to the position of Fig. 49 where it cannot be actuated by its hook 85. Thus, neither the machine clutch nor the card shuttle clutch 90

can be thrown into operation to bring about the operation of the machine cam shafts or the card feed mechanism. The parts will be latched in this position by a spring actuated latch 791 cooperating with the pin 792 which connects the finger 788 with the link 787. When the finger 790 depresses the link 81 the latter is moved to the position of Fig. 50. As heretofore described when the link is in this position depression of the start key will, through the link 94 and the finger 98 in cooperation with the pin 80 cause the link 81 to move to the left and thus bring the card feed clutch into operation. This will cause cards to be fed through a normal card feeding cycle.

At the proper time in this cycle a crank 793 (Fig. 43) raises the rear projection 791a of the latch 791 (see also Fig. 49) thus rocking the latch out of cooperation with the finger 788a. This permits the link 81a to rise into position to be engaged by the hook 85a to institute a series of machine cycles by causing the machine clutch to be thrown into operation.

Where the machine was caused to stop by a misfeeding of either one of the cards, as for instance, the new card, the operator might restart the machine by depression of the start key as just described. This would not only cause another new card to be fed into the machine but would feed the master card already there out of the machine. The stoppage of the machine may have been caused by the fact 10 that the supply magazine was empty or by the fact that a card had slipped out from the card feed clips. If the supply pocket was found to be empty the operator would place a new supply of cards in the pocket and then 15 restart the machine or if a card had slipped from the clips the operator could remove this card from the machine and then restart the machine. In order to save time in the operation of the machine the operator might place 20 a new card in the card frame and then institute a series of machine cycles rather than a card feeding cycle. This would prevent the feeding out of the master card already in operative position and thus save the time of 25 replacing this card in the machine which would otherwise be necessary. The means for bringing about the institution of the machine cycles without the card feeding cycle, includes a special starting button 794 (Fig. 30 14). This button is connected by a shank 795 to an arm 796 (Figs. 43 and 44). This arm is held in its upper position by a spring 797 and when depressed will engage the latch 791. (Figs. 43 and 49) and lower the latch 35 out of cooperation with the pin 792.

This will release the fingers 788 and 790 to permit them to rise and release links 81, 81a. The machine has, of course, stopped at the end of a card feeding cycle and has thus 40 locked the link 81 in its lower position and has released the link 81a to permit the institution of a machine series of cycles. Thus, when the fingers 788 and 790 are now released the link 81a will rise and will be actuated 45 by its latch 85a to cause the machine clutch to be thrown in. The machine will thus commence to operate under control of the master card which was fed into position during the cycle in which the misfeed of the new card 50 took place to bring about the stoppage of the machine.

Position of control plate controls starting of machine

55 In Fig. 22 the frame 465 which carries the control plate 10 is shown in position resting on the cam 471. Means is provided to prevent starting of the machine unless this cam is in the position here shown. This means 60 includes a link 798 connected to the member 475 which in turn is connected to the cam 471. As shown in Figs. 14 and 43 the link 798 is adapted to be moved into position directly 65 above the arm 71 connected with the start and stop keys. Referring to Fig. 22 if the

crank arm 469 is rocked clockwise to rock the cam 471 into position to lower the frame 465 the link 798 will be moved to the left over the arm 71. In this position it will be impossible to depress the start key since depression of the start key causes the arm 71 to rise with the stop key. As long as the cam 471 is in the position of Fig. 22, however, the link 798 will be in its right hand position as shown in Fig. 43 out of the path of the arm 71 so that the start key may be operated.

Successive card feeding cycles

Referring to Figs. 52 and 53 the operation of the card stop or stripper 182 has been 70 described. It will be remembered that at the beginning of a card feeding cycle the cam 188 will actuate the arm 185 to move the stripper 182 to the left out of the path of the master card which is now in the M1 position. The stripper will be latched in this left hand position by the latch member 190. As soon as the rear edge of the card passes the stripper and before the leading edge of the next card reaches this position the latch 190 will 80 be lowered to release the stripper and the spring 189 will move it into position to intercept the incoming card. Normally after a card feeding cycle there will be a series of 85 machine cycles during which the cam 188 on the shaft 66 which is controlled by the machine clutch will operate to move the stripper 90 out of the path of the card. It will be seen that if for some reason it is desired to bring about a card feeding cycle immediately following a similar cycle, the stripper 182 having been released to move into the path of the card will still be in this position and cannot be removed by the operation of a machine 95 cycle since no machine cycle is to follow the last card feeding cycle. Means are therefore provided for moving the stripper out 100 of the path of the cards without effecting a machine cycle operation. It is, of course, understood that when the start key is depressed a card feeding cycle always precedes the series of machine cycles. Fixed on the shaft 96 which as we have seen is rocked when the start key is depressed (Figs. 14 and 44) is an arm 799 (Fig. 53). A link 800 has 105 pin and slot connection with an arm 801 and is held in position by a guide 802 and pulled upwardly by a spring 803. A pin 804 on the link is adapted to be engaged by the arm 799 to move the link downwardly.

110 Arm 801 is fixed on a shaft 805 (Figs. 53 and 43) on which is also fixed an arm 806 connected by a link 807 to arms 808 which in turn are connected by a link 809 to the arm 185. Depression of the stop key will thus 115 rock the arm 799 and move the link 800 downwardly and this in turn through the interconnecting mechanisms will move the card stripper 182 to the left as viewed in Figs. 52 and 53 where it will be latched by 120

70

120

125

130

the number 190. As the link 800 is moved downwardly it will engage a pin 810 and will be cammed out of cooperation with the arm 799. The link will then be raised to its 5 normal position by a spring 803, the pin 804 riding upwardly against the end of the arm 799. When the start key is released and the shaft 96 returns to normal position the pin 804 will snap back under the arm 799. The 10 spring 811 is provided connecting the arm 801 to the link 800 (Figs. 43 and 53) and the connection between the link 800 and arm 801 is a pin and slot connection so that in normal 15 operation when the cam 188 of Fig. 52 operates to move the stripper 182 the clockwise rotation of shaft 805 will cause the spring 811 to stretch without raising the link 800.

While there has been shown and described 20 and pointed out the fundamental novel features of the invention as applied to a single modification it will be understood that various omissions and substitutions and changes in the form and details of the device 25 illustrated and in its operation may be made by those skilled in the art without departing from the spirit of the invention. It is the intention, therefore, to be limited only as indicated by the scope of the following claims.

30 I claim:

1. In a machine of the class described, means for analyzing a perforated record card, printing and perforating means controlled by said analyzing means for printing and perforating upon a separate record sheet and a perforated control plate adapted 35 also to control said printing and perforating means to alternatively effect printing or perforating.

40 2. In a machine of the class described, record perforating means, a plurality of perforated record control plates and means for selecting one of said plates for controlling the operation of said punching means.

45 3. In a machine of the class described, means for analyzing a perforated record card, means controlled by said analyzing means for making entries upon a separate sheet, a plurality of perforated plates adapted 50 to control certain operations of the machine and means for selecting one of said plates for operation.

55 4. In a machine of the class described, means for analyzing a perforated record card, means controlled by said analyzing means for making entries upon a separate sheet and a perforated control plate for determining the place of entry of data upon 60 said sheet.

65 5. In a machine of the class described, means for supporting a perforated record, means for analyzing such record, means for moving said supporting means to cause said analyzing means to analyze predetermined portions of the record card and means for

selectively varying the effect of said moving means.

6. In a machine of the class described, means adapted to support a perforated record, means for analyzing such record, means for moving said supporting means to cause said analyzing means to analyze selected portions of said record, item entering means controlled by said analyzing means for entering items upon a separate record and means for selectively varying the effect of 70 said moving means.

7. In a machine of the class described, means for analyzing a perforated record, supporting means adapted to support a separate record, item entering means controlled by 75 said analyzing means for entering items upon said separate record, means for shifting said supporting means to control the position of entry of data upon said separate record and means for selectively varying the effect of 80 said moving means.

8. In a machine of the class described, means for analyzing a perforated record, supporting means adapted to support a separate record, item entering means controlled by 85 said analyzing means for entering items upon the separate record, a perforated control plate and means controlled by said plate for causing shifting of said supporting means to determine the place of entry of data upon 90 said sheet.

9. In a machine of the class described, means for supporting a perforated record, means for analyzing such record, means for 95 moving said supporting means in a plurality of directions and means for variably and selectively determining the distance of movement of said supporting means.

10. In a machine of the class described, means for supporting a perforated record, means for analyzing such record, means for moving said supporting means in a plurality of directions, means for selecting the direction in which said supporting means shall be 100 moved and means for variably determining the distance of such movement.

11. In a card controlled machine for entering data upon a record during successive cycles of operation of the machine, a control 115 plate adapted to control the operation of the machine during successive cycles and means for shifting the plate to vary the control during the successive cycles.

12. In a perforated card controlled machine means for analyzing a perforated card during successive cycles of operation, a perforated control plate adapted to control the operations of the machine and means for periodically shifting said plate to vary the operations during successive cycles.

13. In a machine of the class described, means for entering data upon a record during successive cycles of operation and a control plate adapted to determine the number 120 125 130

- of cycles of operation required to make the entries.
14. In a machine of the class described, means for analyzing a perforated card, means for making entries upon a separate card, means controlled by said analyzing means for controlling said record entering means and a control plate adapted to determine the number of cycles required for making such 70 entries.
15. In a machine of the class described, means for analyzing a perforated record during a series of cycles of operation of the machine, means controlled by said analyzing 75 means for entering data upon a separate record, a perforated control plate for controlling the operations of the machine during successive cycles and for determining the number of operations required to make the 80 entries.
16. In a machine of the class described, means for analyzing a perforated record during a series of cycles of operation of the machine, means controlled by said analyzing 85 means for entering data on a separate record, a control plate for controlling the operations of the machine during successive cycles and for determining the number of operations required to make the entries, and 90 means for shifting the plate periodically to vary the control thereof during successive cycles.
17. In a machine of the class described, means for feeding record cards to operative 95 position, means for entering data upon said cards and a control plate adapted to control the entering of such data and for determining the distance and direction of the feeding of said cards.
18. In a machine of the class described, means for feeding records to operative position, means for analyzing said records, and a variable control device adapted to control the operations of said analyzing means and 100 also adapted to control the time and extent of operation of said feeding means.
19. In a machine of the class described, means for feeding a plurality of record cards, means for transferring the data from one of 105 the cards to another, a control plate adapted to control said transferring means and means for periodically shifting said control means to vary the control thereof, said shifting means being controlled by said controlling 110 means.
20. In a machine of the class described, a plurality of perforation sensing elements for analyzing perforations in a control card, a perforated control plate adapted to determine 115 which of said elements shall operate and means for shifting said control plate to vary the selection of elements for operation.
21. In a machine of the class described, a plurality of perforation sensing elements for 120 sensing perforations in a record card during successive cycles of operation of the machine and means for locking certain of said sensing elements against operation.
22. In a machine of the class described, printing and punching means for making data entries upon a sheet, means interlocking said printing and punching means to effect printing and punching in predetermined relative position and means for shifting the relative interlocking position of said printing and punching means for varying the relative 125 positions of printing and punching.
23. In a machine of the class described, means for printing upon a record, means for making perforated entries upon said record, means for locking said printing and perforating means in predetermined relative position and means for varying said predetermined relative position.
24. In a machine of the class described, means for sensing data on a record card, printing means controlled by said sensing means for entering data upon a separate 90 card, punching means also controlled by said sensing means for entering data upon said separate card, means interconnecting said printing and punching means to control the relative positions of printing and punching 95 and means for disconnecting said printing and punching means.
25. In a machine of the class described, a record supporting frame, means for feeding records to said frame, means for shifting the position of said frame and means controlled by said frame for preventing said feeding means from operating.
26. In a machine of the class described, a plurality of record supporting frames, means for feeding records to said frames, means for shifting said frames and means controlled by the positions of said frames for controlling said feeding means.
27. In a machine of the class described, a plurality of card holding frames, means for feeding cards to said frames, means for shifting said frames in a plurality of directions and means controlled by the positions of said frames adapted to permit said feeding means to operate only when said frames are in normal positions.
28. In a machine of the class described, sensing elements adapted to sense perforations in a record card to control the operation of the machine, settable members and selecting means controlled by said members for locking certain of said sensing elements against operation.
29. In a machine of the class described, a plurality of sensing elements adapted to sense perforations in a card during successive cycles of operation of the machine and means for locking certain of said sensing elements 130 against operation.

- against operation during predetermined cycles of operation.
30. In a machine of the class described, a plurality of sensing elements for sensing perforations in a record card during successive cycles of operation, means for determining which of said elements shall operate during the successive cycles and settable means for controlling the operation of said determining means.
31. In a machine of the class described, means for sensing perforations in a record card, controlling means including combs for analyzing said sensing means and for controlling the entering of data upon a separate record and means for locking certain of said combs against operation to vary the control of the combs upon said record entry means.
32. In a machine of the class described, a start key, means controlled by said key when the parts of the machine are in predetermined position for causing the machine to operate and other means controlled by said key when said parts are in a different position to cause the machine to operate.
33. In a machine of the class described, means for feeding cards to and from operative position, means for preventing the feeding of cards when certain parts of the machine are in predetermined position and means for rendering said preventing means inoperative, to permit the feeding of cards when such parts are in such predetermined position.
34. In a machine of the class described, a type bar, a plurality of type elements carried by said bar, means for moving the bar to selectively bring said elements to printing position, means for actuating one of said type elements for printing and means for preventing the movement of said type bar when one of said type elements is out of normal position.
35. In a machine of the class described, means for holding records in operative position, means for moving said holding means to various positions, a perforated control plate adapted to control the operations of the machine, means for moving said control plate into and out of operative position and means for preventing the movement of said plate out of operative position when said holding means is out of normal position.
36. In a machine of the class described, a plurality of operation control plates for controlling the operations of the machine, means for selectively placing one of said plates in selected position, means for moving the selected plate into operative position and means for preventing the operation of said moving means when said selected plate is out of selected position.
37. In a machine of the class described, means for analyzing perforated record cards, means controlled by said analyzing means for making entries upon a new card and a frame convertible to hold new cards of a plurality of different sizes.
38. In a machine of the class described, a type carrier having a plurality of type elements, means for moving the type carrier to set any of the elements in a selected one of a plurality of printing positions, a type feeler adapted to be controlled by one of said type elements when in non-restored position to control the operation of the machine and means for adjusting said feeler to operate in connection with either of the printing positions.
39. In a machine of the class described, means for analyzing a perforated record, means for printing data upon a record, translating mechanism controlled by said analyzing means for controlling said printing means and a perforated control plate adapted to control said translating mechanism.
40. In a machine of the class described, means for analyzing a perforated record card, means for perforating a separate record card, translating mechanism controlled by said analyzing means and adapted to control said perforating means and a perforated control plate adapted to control said translating mechanism for selectively transferring data from said first named card to said second named card.
41. In a machine of the class described, means for analyzing a perforated record card, mechanism for printing and punching data upon a second record card, converting mechanism controlled by said analyzing means for controlling said printing and punching mechanism and a perforated control plate adapted to selectively control said converting mechanism to effect a selective transfer of data from said first named card to said second named card.
42. In a machine of the class described, means for analyzing a record sheet, means for printing and punching data upon a separate record sheet, converting mechanism controlled by said analyzing means for controlling said printing and punching means and a control plate adapted to selectively control said converting mechanism to control the transfer of data from said first named sheet to said second named sheet.
43. In a machine of the class described, means for analyzing a perforated record sheet, means for making entries of items upon a separate sheet converting mechanism controlled by said analyzing means for controlling said entry making means and a perforated control plate adapted to control said converting mechanism for effecting a selection of data taken from said first named sheet for entry upon the second named sheet.
44. In a machine of the class described, means for analyzing a perforated record card, means for making record entries upon

a separate card, said record making means being controlled by said analyzing means, a control plate having a plurality of fields of control perforations for varying the control 5 of said analyzing means upon said record making means and means for causing said fields to control the operation of the machine in predetermined order.

45. In a machine of the class described, 10 means for printing data upon a record card, means for punching data upon such card in a predetermined position relative to the printed data and means for varying in relative positions of the printed and punched 15 data.

In testimony whereof I hereto affix my signature.

JOHN ROYDEN PEIRCE.
